cago, Ill., a corporation of Delaware

Application June 19, 1933, Serial No. 676,439

26 Claims. (Cl. 179—26)

The present invention relates to telephone systems in general, but is concerned more particularly with semi-automatic telephone systems whereby connections between manual lines entering an exchange may be set up by automatic switches under the control of an operator at a switchboard in a remote exchange.

The main object of the invention is the production of new and improved circuit arrangements for simplifying and improving the operation in semi-automatic magneto telephone systems of the type disclosed in U. S. Patents Nos. 1,752,543 and 1,801,368 issued to L. L. Ruggles and E. S. Peterson et al. on April 1, 1930, and April 21, 1931, respectively.

In each of the above patents connections are set up between manual magneto lines by automatic switching apparatus responsive to control exercised over a control trunk extending between the manual magneto exchange and a remote operating center. This type of system was designed to improve service in rural communities by making it possible for a remote operator, instead of a local operator, to control the connections. The design is intended to retain, to as great a degree as possible, the same method of operation as was formerly used in connection with the old manual board. The remote operator can give practically the same service to the subscribers as could the local operator and can give the service in very much the same manner, the chief difference being that she operates a dial instead of plugging up cords. This equipment is intended to replace manual magneto switchboards which cannot profitably carry the cost of a local operator.

The general operation of this type of system is as follows: A local subscriber, upon initiating a call by turning his hand generator, causes a finder in the local exchange to find his line and signal the remote operator over a control trunk extending to the remote operating center or main exchange. The remote operator answers the call, dials back over the same control trunk thereby establishing the desired connection to the local called line, and then rings the party. The remote operator then retires from the local connection and either the local calling or called party can release the local connection by turning the hand generator. Calls to and from other distant exchanges are handled the same as local subscriber calls because the trunk lines to such exchange terminate in equipment the same as local magneto lines.

1. One of the features of the invention relates to the circuit arrangements in which the remote

operator, when extending a call for a local calling party, can enter a local completed telephone connection which tests busy in order to determine if the local subscribers have failed to release such connection by ringing down at the close of conversation and wherein the calling party cannot hear the conversation on the completed connection in case the connection is still in use.

2. Another feature relates to the means whereby the remote operator can remove the busy tone when she listens in on a busy line for the purpose of holding the calling party on the line for completing the desired connection.

3. A further feature relates to the circuit arrangements whereby the remote operator can release a busy local connection from the line she has called and then ring the called party to complete the desired local connection between the local calling and called parties.

4. Another feature relates to means whereby the remote operator can, while completing a connection for the calling party, split the local connection so that she can talk to either the local called or the local calling party without the other hearing such conversation.

5. An additional feature relates to the circuit arrangements for storing calls and for notifying the remote operator by a tone that additional calls are waiting in a system wherein local connections are completed through the medium of a single control trunk extending to the remote operator.

6. Another feature relates to the means whereby a remote operator can originate a call and complete a local connection to local subscribers even though the call has not been initiated by a local party.

7. Another feature relates to the local connector which, when operated to a trunk level, converts its circuits so that the control operator may directly step the connector step by step until she has found an idle trunk line in this particular level.

8. A further feature relates to the novel circuit arrangements whereby an audible signal is transmitted over the control trunk from the local exchange to the remote operator to identify a local calling paystation line.

9. Another feature relates to the means whereby the operator's control trunk is automatically connected to either one of two identical units of equipment when the capacity of a remote controlled exchange (RCX) is greater than one unit.

10. A further feature relates to the circuit arrangements whereby the control trunk extending

from the local exchange (RCX) to the operating center may be only a single wire using a ground return.

Other objects and features of the invention will be apparent upon a further perusal of the specification in connection with the detail description of the accompanying drawings in which Fig. 11 shows the manner in which the various sheets of drawings are arranged while Figs. 1 to 10, inclusive, show the detail circuits.

Referring now to Fig. 1: The lower left-hand circuit diagrammatically represents a plurality of well-known magneto substation circuits in which the ringers thereof may be connected to either line conductor and ground or may be bridged across the line conductors. The center left-hand circle diagrammatically illustrates magneto paystation lines while the upper circle represents a jack and ring down trunk terminating in a distant manual exchange. LC shows the line circuit for the regular magneto lines and LC-1 the line circuit for the paystation magneto lines. LC-2 is the line circuit for the trunk extending to the distant manual exchange and is similar to the line circuit LC. LC-3 is the line circuit for permitting the remote control operator at the operating center to initiate calls and to test. PST represents the relay group associated with the paystation magneto lines for generating a paystation tone. The finder switch F is of the well-known rotary type in which the wipers move step by step on the deenergization of its motor magnet and in which the wipers remain in the position last used.

Fig. 2 represents the local connector permanently associated with the finder F and the ringing machine RM. The local connector is of the well-known Strowger type having vertical and rotary movements. The normal post springs TOLL-PS1 operate when the connector is operated to the level in which the toll trunks terminate while the normal post springs TRK-PS2 operate when the connection is operated to the level in which the trunk lines to distant exchanges terminate.

The ringing machine RM shown in the lower left-hand corner comprises the usual ringing transformer T and a group of relays one of which has a vibrating armature.

Fig. 3 shows the distributor for preselecting idle local finder connector links shown in Figs. 1 and 2. The distributor comprises a well-known step-by-step rotary switch similar in construction to the finder F and an associated group of relays.

Fig. 4 shows the common equipment comprising a group of relays which are common to all the local finder connector links for controlling functions to be described in detail herein-after.

Fig. 5 shows a supervisory switch for enabling the remote operator at the remote operating center to supervise in a manner to be described later. This switch is also of the well-known rotary step-by-step type. The relays 401, 403, and 409 comprise a switching arrangement whereby when two similar systems, one of which is shown, are provided the control trunk coming from the operating center can be switched to either system. An emergency operating center indicated by the square in the center of the drawing is somewhat similar to the remote operating center shown in the dotted rectangle in the lower left-hand corner. The equipment located at the remote operating center comprises

the usual operator's head set drop, calling device CD, repeating coil RC2 and the ringing, monitoring and connecting keys.

Fig. 6 is somewhat similar to Fig. 4 and is to be substituted for Fig. 4 when a single grounded control wire is used for a control trunk to the remote operating center. This single wire control trunk may be grounded phantom taken from a metallic toll trunk if desired.

Fig. 7 is somewhat similar to Fig. 5 and is to be substituted for Fig. 5 whenever Fig. 6 is to be used.

Fig. 8 shows a jack ending toll trunk TT terminating in either the remote operating center or another distant exchange. The equipment comprises the usual jack J, drop D, calling device CD, buzzer 704, dry cells DC, repeating coil and the holding, dialling, monitoring and ringing keys. The toll trunk TT is accessible from the local connector banks by way of conductors 161 to 164, inclusive, which terminate in the toll levels of the local connector banks.

Fig. 9 shows the toll connector which is of the well-known Strowger type having vertical and rotary movements. The toll connector is located in the local remote controlled exchange (RCX) and has its bank contacts multiplied with the banks of the local connector shown in Fig. 2.

Fig. 10 shows a group of relays for use with the common control equipment shown in Fig. 6 when divided ringing is to be employed.

This system is primarily a fifty-line unit although two fifty-line units can be connected together to form a one-hundred-line board. Each fifty-line unit may, when required, be equipped with ten local finder-connector links and one or more toll connectors. The two fifty-line units are operated separately and each unit may be switched to the control trunk when required. Each fifty-line unit will have one distributor and one common relay control group.

Having given a general description of the system and drawings, a detailed description of the circuit operations will now be explained.

For this purpose it will be assumed that one of the regular magneto subscribers wishes to be connected to another local station. The subscriber operates the hand generator at his telephone in the usual manner, projecting ringing current over his line conductors 22 and 23 and through the upper winding of relay 11. This ringing current passing through the upper winding of line relay 11 causes the energization of such relay which thereupon at armature 13 connects negative battery through the winding of cut-off relay 12 to the fourth bank contact accessible to the finder wiper 61. At armature 14 relay 11 closes a circuit extending through the lower winding of line relay 11, armature 18 and finder start conductor 30, through the normally closed springs controlled by armature 217 and through the winding of slow-to-operate start relay 201. Line relay 11 immediately locks itself over this circuit and after an interval of time start relay 201 becomes operated. At armature 15 line relay 11 opens a point in its original energizing circuit. Start relay 201, upon energizing, at armature 212 completes a circuit for energizing the slow-to-operate relay 202 and at armature 213 completes a circuit for energizing slow-to-operate relay 203 in case the wipers of the distributor are standing on an idle finder connector link. Since the distributor is of the preselecting type, guard wiper 255 should therefore be in engagement with an idle finder-connector link with

which negative battery is connected through the guard lead 65 terminating in the first bank contact accessible to guard wiper 255. At this time a circuit may now be traced for energizing relay 203 as follows: from grounded armature 414, conductor 262, armature 232 and its resting contact, conductor 273, armature 328, conductor 274, armature 237 and its working contact, armature 245, armature 213, through the winding of relay 203, interrupter springs 254 and through the winding of motor magnet 253 to battery. Relay 203 after an interval energizes over the above-traced circuit but the motor magnet 253 on account of the high resistance in the winding of relay 203 is prevented from energizing at this time. Slow-to-operate relay 202, upon energizing, at armature 214 connects ground to conductor 277; at armature 215 connects battery through resistance 216 to conductor 276; and at armature 218 closes a shunt around the armature 213 to maintain the relay 203 in energized position. Relay 203, upon energizing, at armature 219 connects ground to the chain conductor 69 to maintain the relay 208 in energized position; at armature 220 completes a circuit for energizing the finder motor magnet 64; at armature 221 opens the preselecting stepping circuit to the motor magnet 253 and prepares a circuit for grounding the guard conductor 65; at armature 222 closes a circuit for energizing the vibrating relay 205; and at armature 223 closes a point in the finder testing circuit. The circuit for energizing the motor magnet 64 of the finder may be traced as follows: from grounded armature 220, armature 223 and its resting contact, armature 227, wiper 257 in engagement with its first bank contact, conductor 67, and through the winding of motor magnet 64 to battery. Magnet 64 energizes over the above-traced circuit and at springs 63 grounds the conductor 66 engaged by wiper 256 for energizing the stepping relay 206. Stepping relay 206, upon energizing, at armature 227 opens the circuit extending to the motor magnet 64, whereupon the magnet 64 deenergizes and advances the wipers of the finder F one step in engagement with the next set of contacts terminating the next magneto subscriber's line. Magnet 64 in addition to operating the wipers of the finder one step also interrupts the circuit extending through the upper winding of stepping relay 206 with the result that the stepping relay 206 again deenergizes and at armature 227 reestablishes the circuit for energizing the motor magnet 64. This interaction between stepping magnet 64 and stepping relay 206 continues until such time as the test wiper 61 encounters a bank contact marked with negative battery thereon through the winding of the associated cut-off relay in the line circuit. As soon as test wiper 61 encounters the marked bank contact, or in case the wiper 61 has been sitting on the fourth bank contact, a circuit is completed for energizing the cut-off relay 12, the test relay 207, and the stepping relay 206 in a series circuit as follows: from grounded armature 415 (Fig. 5), conductor 260, armature 223, through the lower winding of stepping relay 206, through the upper winding of test relay 207, wiper 258, conductor 68, finder wiper 61, fourth bank contact accessible to wiper 61, conductor 24, armature 13, and through the winding of cut-off relay 12 to battery. Stepping relay 206 at armature 227 prevents further rotation of the finder by opening the motor magnet circuit in case the wipers of the finder have been sitting 75 on the fourth bank contact and in case the

wipers have been rotated to this bank contact the operation of armature 227 prevents the energization of motor magnet 64. Cut-off relay 12 energizes over the above-traced circuit and at armature 16 opens a further point in the original energizing circuit of line relay 11; at armature 18 opens the locking circuit of relay 11 extending to start conductor 30 whereupon line relay 11 and start relay 201 deenergize; and at armature 17 closes a locking circuit for itself by way of conductor 24, test wiper 61, to the grounded hold conductor 68. Test relay 207, upon energizing over the above-traced circuit, completes a circuit for energizing motor magnet 253 by way of armature 220 and armature 228 and its working contact, while at its resting contact opens a further point in the energizing circuit of the finder magnet 64. At armature 230 grounds the guard conductor 65 by way of grounded armature 230, working contact of armature 221 and said armature, armature 225, wiper 255, start conductor 65, and thence by way of spring 123 and its resting contact in the local connector, spring 125 and its resting contact, through the winding of hold relay 103 to battery, and through the normally closed springs controlled by armature 140 of relay 105 through the winding of connecting relay 104 to battery. The hold relay 103 and the connecting relay 104 are energized over this circuit to prepare the connector for operation as will be described hereinafter. At armature 231 relay 207 completes a locking circuit for itself extending from grounded armature 326 and its resting contact, and conductor 264 through the lower winding of relay 207 to battery. Armature 231 also grounds conductor 261 to energize relay 407 to prevent a call on the second fifty-line unit from switching the control trunk, comprising conductors 453 to 454, into the second unit. This is accomplished by relay 407 energizing and disconnecting ground from conductors 260' and 262' by the operation of armatures 411 and 412; it being understood that the conductors 260', 261', and 262' are connected to the second unit in the same manner as conductors 260, 261, and 262 in the first unit are connected. At armature 232 relay 207 opens the energizing circuit of relay 203 at its resting contact and at its working contact connects the grounded conductor 262 to conductor 263 for energizing slow-to-release relay 430, Fig. 5, by way of the normally closed springs controlled by armature 431. Relay 430 energizes over the above-traced circuit and at armature 433 closes a circuit for energizing the slow-to-operate relay 431. At armature 433 relay 430 connects ground to conductor 451 and at armature 431 connects negative battery through a resistance to conductor 452. A circuit may now be traced over the two trunk conductors 453 and 454 extending to the remote operating center for causing the energization of the drop to signal the operator. This circuit may be traced as follows: grounded armature 432, conductor 451, resting contact of armature 429 and said armature, trunk conductor 454, through the upper right-hand winding of the repeating coil RC2, spring 461 and its resting contact, through the winding of the drop, through the lower right-hand winding of repeating coil RC2, trunk conductor 453, armature 419 and its resting contact, conductor 462, and armature 481 and its resting contact through the resistance to battery. A short interval thereafter slow-to-operate relay 431 energizes and completes a locking circuit for itself from grounded conductor 264 by way of armature 75

438. At armatures 434, 435, and 436 relay 431 disconnects the supervisory switch wipers 404, 405, and 406 from the control trunk and at armature 437 opens the energizing circuit of slow-to-release relay 430 which after an interval of time deenergizes and connects the left-hand windings of the repeating coil RC1 to the trunk conductors 453 and 454 by way of armatures 432 and 481.
- 10 Returning now to the point in the circuit description where the distributor magnet 253 energized as a result of the energization of test relay 207, said magnet at springs 254 also opens a point in the circuit of relay 203 which accordingly deenergizes after an interval. At armature 219 relay 203 disconnects ground from the all-trunk-busy relay 208 but this relay is still maintained energized over the chain conductor 69 extending from all of the idle finder connector links. At armature 220 relay 203 opens the circuit of magnet 253 whereupon the magnet deenergizes and advances the wipers of the distributor one step. At armature 221 relay 203 closes a self-interrupting circuit for the stepping magnet 253 to the guard conductor 65. In case the wiper 255 should be in engagement with a guard conductor such as 65 extending to a busy finder connector link, then ground will be on this guard conductor with the result that a circuit may be traced from the 25 grounded guard conductor, wiper 255, armature 225, armature 221 and its resting contact, interrupter springs 254, and through the winding of magnet 253 to battery. Magnet 253 energizes and at the end of its stroke opens the spring 254 to interrupt its own circuit whereupon the magnet deenergizes and advances the wipers of the distributor switch another step. This interrupter action of the motor magnet 253 continues until the guard wiper 255 no longer encounters a 30 grounded bank contact. All finder connector links which are busy will have ground connected to their guard conductors 65 while the idle finder connector links will have negative battery connected to their guard conductors. The distributor is therefore operated to preselect an idle 35 finder connector link. At armature 222 relay 203 opens the circuit of relay 205 with the result that relay 205 deenergizes and at the vibrating spring 226 opens the circuit of slow-to-operate relay 204 before relay 204 has had sufficient time to 40 energize. It should probably be mentioned at this time that the armature 226 vibrates for a pre-determined length of time before it permanently closes the circuit to relay 204 and since relay 204 is a slow-to-operate relay said relay will not 45 energize as long as the armature 226 is vibrating. At armature 223 relay 203 opens the circuit of stepping relay 206 and test relay 207 with the 50 result that the stepping relay 206 deenergizes while the test relay is held locked over its lower winding as previously described.
- 55 Referring now to the local connector shown in Fig. 2 and at a time when relays 103 and 104 were energized as a result of the energization of the distributor test relay 207, relay 103, upon energizing, at armatures 115 and 119 prepares a circuit for connecting the calling subscriber to the right-hand windings of the repeating coil RC. This circuit may be traced from the magneto telephone line shown in Fig. 1 extending by way of conductors 22 and 23, wipers 60 and 62 of the finder S, conductors 72 and 73, armatures 115 and 119 to armatures 143 and 147. At armature 116 relay 103 connects ground to hold conductor 68 to maintain the cut-off relay 12 in the subscriber's 60 line circuit LC in energized position and to mark the calling line busy to the finders and connectors having access thereto. At armature 117 relay 103 opens one of the grounded connections extending from the local connectors in normal position from the chain conductor 69. The all-trunks-busy relay 208, however, is maintained energized as long as there is an idle finder connector link. At armature 118 relay 103 completes a locking circuit for itself extending from grounded armature 112 and this ground also maintains the connecting relay 104 in energized position. Armature 118 also maintains this ground on guard conductor 65 to maintain this finder connector link busy and inaccessible to the distributor shown in Fig. 3. 15 At armature 120 relay 103 opens a point in the circuit extending to the release magnet 109.
- 20 Connecting relay 104, upon energizing, at armatures 127 and 137 connects the calling subscriber's line to the operator's control trunk over the following circuit: from the subscriber's line as previously traced to armatures 143 and 147, armatures 127 and 137, conductors 185 and 186, resting contacts of armatures 329 and 331 and said armatures, conductors 268 and 269, through the right-hand windings of the repeating coil RC1, and from thence by way of the left-hand winding of the repeating coil RC1, resting contacts of armatures 432 and 481, conductors 451 and 452, resting contacts of armatures 419 and 420, conductors 453 and 454 extending from the local remote controlled exchange to the distant operating center, and thence through the right-hand windings of the repeating coil RC2 in the distant or remote operating center. At armature 128 relay 104 prepares a point in the circuit whereby the operator may transmit ringing current over wiper 151 to ring all of the magneto subscribers' substations having their ringers connected to the negative side of the line to ground. 30 In a similar manner armature 130 prepares a point in the positive ringing circuit whereby the operator may ring the magneto lines over the positive wiper 154 on the subscribers' lines having their fingers connected to the positive side of line and ground. At armature 129 relay 104 prepares a point in the circuit extending to the test relay 310 in the common equipment in Fig. 4; at armature 130 prepares a point in the circuit extending to the vertical magnet 111; at armature 131 prepares a point in the circuit for energizing cut-through relay 105; at armature 132 prepares a point in the circuit for energizing relay 106; at armature 133 prepares a point in the circuit for directly rotating the connector in search of an idle trunk; at armature 134 prepares a point in the circuit extending to the rotary magnet 110; and at armature 135 prepares a point in the circuit for energizing slow-to-operate relay 102. 40
- 45 When the operator observes the operation of the drop at her position indicating a call, she will operate the key K which at springs 460 and 464 connects her telephone set to the left-hand windings of the repeating coil RC2 to complete the talking circuit to the calling subscriber over the path previously traced. At spring 461 and its resting contact the circuit for operating the drop is opened and at the make springs on springs 461, 462, and 463 ground through the impulse springs of the calling device CD is connected to both 50 trunk conductors 453 and 454 through the right hand windings of repeating coil RC2. A circuit may now be traced for energizing relays 303 and 304 in the common equipment, Fig. 4, as follows: from ground through the impulse springs of the 55
- 60
- 65
- 70
- 75

calling device CD, springs 463, springs of the monitor key MK, springs of the positive ring key, springs 462, lower right-hand winding of repeating coil RC2, conductor 453, armature 419 and its resting contact, conductor 452, armature 481 and its resting contact, lower left-hand winding of repeating coil RC1, conductor 271, through the lower winding of differential relay 381, and through the windings of relay 303 and 304 in series to battery.

10 At the same time another circuit may be traced for energizing line relay 302 in the common equipment as follows: from ground through the impulse springs of the calling device CD, springs 463, normally closed springs controlled by the negative ring key, working contact of spring RC2, conductor 454, armature 420 and its resting contact, conductor 451, armature 432 and its resting contact, upper left-hand winding of repeating coil RC1, conductor 270, through the upper winding of differential relay 301, and through the winding of line relay 302 to battery. Differential relay 301 does not energize over the above-traced circuit because both windings oppose each other. Line relay 302, upon energizing, at armature 318 and its working contact completes a circuit for energizing slow-to-release relay 305 which relay thereupon energizes and at armature 322 and its resting contact disconnects ground from conductor 266 and at its working contact grounds conductor 267 to maintain relay 431 in energized position and to maintain the conductor 264 grounded by way of armature 439. At armature 323 relay 305 closes an obvious circuit for energizing relay 306 and connects ground to conductor 70 to energize the vibrating relay 81 in the paystation tone relay group shown in Fig. 1. At armature 324 relay 305 prepares the impulsing circuit. Relay 303, upon energizing, at armature 319 and its working contact closes an auxiliary circuit for maintaining the slow-to-release relay 305 in energized position and at its resting contact opens a point in the circuit to the positive ring relay 309; and at armature 320 prepares a point in the circuit to the monitor relay 307. Marginal relay 304, upon energizing over the above-traced circuit, at armature 321 opens a point in the circuit to the monitor relay 307. Slow-to-release relay 306, upon energizing, at armature 325 prepares a point in the circuit to the cut-through relay 105 or release relay 102 dependent upon the position of the test relay 310; at armature 326 and its resting contact disconnects ground from conductor 264, which conductor, however, is grounded by the operation of armature 322 over conductor 267 and armature 439, and at its working contact grounds conductor 71 to energize the start relay 170 of the ringing machine shown in Fig. 2. At armature 327 relay 306 connects ground through the upper operating winding of test relay 310 to prepare the test circuit and also operates the armature 328 without effect at this time.

Start relay 170 of the ringing machine RM, upon energizing, at armature 174 grounds conductor 78 to energize the differential relay 45 in the paystation tone relay group in Fig. 1, whereupon the differential relay energizes and at armature 49 completes a circuit through its upper differential winding to deenergize such relay whereupon the armature 49 is opened, with the result that the relay is again energized over its lower winding. Differential relay 45 therefore energizes and deenergizes in the manner of a buzzer to generate a tone which is connected to all of the paystation lines by the operation of the paystation relay 43.

75 A predetermined time after the relay 81 is ener-

gized the vibrating armature is maintained in operated position with the result that the slow-to-operate relay 45 energizes. Since the weighted armature 80 continues to vibrate for a considerable time the slow-to-operate relay 45 will not be operated until a certain period of time has elapsed since the energization of the vibrating relay 81. Relay 45 opens the locking circuit of relay 43 at armature 48 with the result that relay 43 now deenergizes to disconnect the paystation tone. It may be mentioned at this time that whenever a paystation line originates a call the relay 43 is energized in parallel with the locking winding of the subscriber's line relay, such as relay 31, and at armature 46 connects the tone created by the differential relay 45 to the negative line conductor to inform the control operator that a paystation subscriber is calling.

When relay 170 energizes and closes its armature springs 175, a circuit is closed for relays 171 and 173 in parallel. Relay 171 being a slow-to-operate relay is not immediately energized but relay 173 is energized by way of armature 177 to start the pendulum 182 vibrating. After a short interval of time slow-to-operate relay 171 energizes and at armature 176 completes a circuit through the lower winding of relay 172 which is rendered slow to operate because of the normal short circuit through its upper winding at armature 179, and at armature 177 and its working contact closes a short circuit around relay 173 from the vibrating armature 182 and springs 184. At armature 177 and its resting contact relay 171 includes the resistance 180 in the energizing circuit of relay 173. Due to the short circuit around relay 173 said relay deenergizes and causes the pendulum to vibrate. After a time which is sufficient to allow the pendulum to pick up speed and vibrate at its full amplitude the slow-to-energize relay 172 energizes and connects the vibrating springs 181 and 183 to the right-hand windings of the ringing transformer T by way of armatures 178 and 179. After this is done, each backward swing of the pendulum results in a circuit being closed for the upper section of the primary winding of the transformer T and each forward swing results in a circuit being closed for the lower section of the primary winding and, consequently, an alternating current is driven through the secondary winding of the transformer T.

Returning now to the time in which the calling subscriber originated the call by operating the relays 201 and 202 in the distributor in Fig. 3, a description will be given of the operation of these relays to transmit a tone to the calling subscriber until such time as the finder finds the calling line. When relay 201 energizes over the start conductor 30, as previously described, said relay at armature 212 completes a circuit for energizing the slow-to-operate relay 202 and the latter relay after an interval of time energizes and at armature 217 connects direct ground to the start conductor 30 and also opens the circuit to relay 201. After an interval of time relay 201 deenergizes and opens the circuit of relay 202 with the result that the latter relay deenergizes and reestablishes the circuit for relay 201. These relays interact in this manner and generate a tick tone through the normally closed spring controlled by armature 217 by the connection of direct ground to conductor 30 and the inductive kick from the winding of relay 201. This tick tone circuit extends back over the finder start conductor 30 through armature 18, armature 14, and the lower winding of line relay 11 to bat-

ter. This tone is thereby induced from the lower winding into the upper winding and is thereby transmitted to the calling subscriber by way of armature 16 and the negative talking conductor 22. In addition at armatures 214 and 215 ground and negative battery is connected to conductors 277 and 276 in order to transmit a waiting tone to the control operator at a time she is extending a prior connection and which tone is transmitted to the control operator over the control trunk extending to the operating center at a time when the test relay 310 in the common equipment, Fig. 4, is operated during such prior call. This waiting tone is connected to the conductors 268 and 269 by the operation of test relay 310 at armatures 351 and 353 and extends by way of the repeating coil RC1, the talking conductors 451, 452, 453, and 454 to the repeating coil RC2 at the remote operating center.

All of the foregoing operations have occurred as the result of a subscriber initiating a call and in response to the control operator operating her dial and answer key K. The operator now challenges the call and receives the number of the line to be called. After receiving the number of the desired called subscriber the operator will operate the calling device CD in accordance with the first digit of the called number. In response to the operation of the calling device the impulse springs interrupt the circuit of relays 302, 303, and 304 with the result that these relays deenergize each time the impulse springs of the calling device CD are opened over the circuit previously traced for said relays. The operation of relays 303 and 304 at this time is without effect. At armature 318 and its resting contact line relay 302, upon each deenergization, completes a circuit for energizing the series relay 315 and vertical magnet 111 as follows: from ground by way of armature 318 and its resting contact, armature 317 and its resting contact, armature 324, armature 357, armature 361, through the winding of series relay 315 in parallel to battery, and thence by way of armature 364 and its resting contact, conductor 190, armature 130, and through the winding of vertical magnet 111 to battery. The slow-to-release series relay 315 is energized in response to the first received impulse and maintains its armatures in attracted position throughout the impulse series. At armature 370 relay 315 closes a shunt around armature 361 and at armature 369 and its working contact completes a circuit for energizing relay 314. Relay 314, upon energizing, at armature 367 completes a circuit for energizing relay 312 by way of armature 365 and at armature 368 and its resting contact opens a point in the circuit to test relay 310 and at its working contact prepares a point in the circuit for the busy relay 311. Relay 312, upon energizing, at armature 363 and its working contact completes a short circuit around relay 313 to prevent its operation during the dialling period. This circuit may be traced as follows: ground by way of armature 327, armature 363 and its working contact, through the winding of relay 313, armature 365, to grounded armature 367.

In the local connector the vertical magnet 111 is operated by each impulse to step the wipers of the local connector in a vertical direction. The wipers of the local connector are therefore operated step by step and stop opposite the level in which the desired called line terminates. Upon the first vertical step of the wiper shaft the off-normal springs 121, 122, and 125 are operated. Off-normal springs 121 prepare a circuit for the

release magnet 109 which, however, is opened at armature 120 at this time; off-normal springs 122 disconnect one of the ground connections extending from the chain conductor 69; and off-normal springs 125 disconnect the guard conductor 65 from relays 103 and 104, which relays, however, are maintained in operated position at this time from grounded armature 112 while at the working contact of off-normal springs 125 the guard conductor 65 is grounded to maintain this 10 finder connector link busy.

At the termination of the first series of impulses transmitted relays 302, 303, and 304 are maintained in their operated position. Relay 305, due to its slow-releasing characteristic, does not de-energize during the transmission of impulses. Shortly after the first series of impulses series relay 315 deenergizes and at armature 369 opens the circuit of relay 314 which thereupon deenergizes. Relay 314, upon deenergizing, at armature 367 removes the short circuit from around relay 313 with the result that this relay now energizes in series with relay 312 over the following circuit: from ground by way of armature 327, armature 363 and its working contact, and through the windings of relays 313 and 312 in series to battery. Change-over relay 313, upon energizing, at armature 364 and its resting contact opens the impulsive circuit extending to the vertical magnet 111 and at its working contact prepares the impulsive circuit to the rotary magnet 110; at armature 365 opens a point in the previously traced short circuit for said relay, and at armature 366 prepares a circuit for directly operating the rotary magnet in case the connector is operated 35 to trunk or toll levels.

The control operator now dials the second digit of the called number with the result that the line relay 302 and relays 303 and 304 follow the impulses as previously described. Relay 305, 40 due to its slow-releasing characteristic, is maintained energized during the impulsive period by the intermittent operation of armature 318. Each time line relay 302 deenergizes a circuit may be traced for operating the rotary magnet 110 45 as follows: from ground by way of armature 318 and its resting contact, armature 317 and its resting contact, armature 324, armature 357, armature 361, through the winding of slow-to-release series relay to battery and also by way of 50 armature 364 and its working contact, conductor 195, armature 134, and through the rotary magnet 110 to battery. Rotary magnet 110, upon operating, rotates the wipers of the local connector into engagement with the bank contacts 55 terminating the called line. Series relay 315 energizes as previously described and at armature 370 closes a shunt around armature 361 to prevent the operation of the busy relay from opening the rotary impulsive circuit and at armature 369 again completes the circuit for relay 60 314. Relay 314, upon energizing, at armature 362 disconnects the busy tone; and at armature 368 opens a point in the circuit to the test relay 310 and at its working contact prepares a circuit 65 for the busy test relay 311.

The operation is now dependent upon whether the called line is busy or idle. In case the called line is idle no circuit is completed for the busy test relay 311 during the time relays 315 and 70 314 are in energized position. Shortly after the rotary impulses relay 315 deenergizes and in turn deenergizes relay 314. The deenergization of relay 314 at armature 368 and its resting contact completes a circuit for the test relay 310 which 75

now energizes over the following circuit: from ground by way of armature 327, through the upper winding of test relay 310, resting contact of armature 368 and said armature, conductor 189, armature 129, wiper 152 in engagement with the test contact terminating the called line, and through the winding of the cut-off relay, similar to relay 12 in Fig. 1, to battery. The cut-off relay individual to the called subscriber's line and the test relay 310 energize over the above-traced circuit. The cut-off relay, such as relay 12, upon energizing, at armature 16 disconnects the line relay, such as line relay 11, from the line conductors of the called line and at armature 18 opens a point in the circuit extending to the finder start conductor 30. At the armature corresponding to armature 17 the cut-off relay completes a circuit for busying the called line in the banks of the finder F. Test relay 310, upon energizing in series with the cut-off relay of the called subscriber's line, at armatures 351 and 353 prepares a circuit for transmitting a waiting tone to the control operator in case a second calling subscriber may be calling at this time. As previously described, it will be remembered that relays 201 and 202 intermittently operate when a subscriber initiates a call and therefore relay 202 at armatures 214 and 215 intermittently connects ground and battery through resistance 216 to conductors 277 and 278. A circuit may now be traced through the armatures 351 and 353 to the heavy talking conductors 268 and 269 and thence through the right-hand windings of the repeating coil RC1 which includes a tone in the left-hand winding of such repeating coil and thence over the conductors 451 and 452, trunk conductors 453 and 454, to the right-hand winding of the repeating coil RC2 and thence over the heavy talking conductors from the left-hand winding to the operator's telephone set. The operator, upon hearing this tone, is advised of the fact that a second calling subscriber is waiting to be served. Relay 310, at armatures 352 and 354, prepares a point in the bridged talking and listening circuit as will be more fully explained hereinafter, at armature 355 and its resting contact opens a point in the release circuit extending to the local connector over conductor 195 and at its working contact prepares a point in the circuit to the cut-through relay 105 also in the local connector. At armature 356 relay 310 closes a locking circuit through its lower winding from grounded armature 327 and at armature 357 opens a point in the impulsive circuit. The called line is temporarily marked busy through the upper winding of relay 310 over the previously traced circuit for energizing the cut-off relay and test relay 310 from ground at armature 327.

The ringing operation performed by the control operator is now dependent upon whether the called subscriber has his ringer connected to the negative line conductor and ground, whether the ringer is connected to the positive line conductor and ground, or whether the ringer is bridged across the two line conductors. If the called subscriber's ringer is connected to the negative line conductor and to ground, then the control operator operates the negative ring key in accordance with the code of the called subscriber's number. Responsive to the operation of the negative ring key, ground extending from the impulse springs of the calling device CD is disconnected from trunk conductor 454 thereby causing the deenergization of line relay 302 and the ener-

gization of differential relay 301. A circuit may now be traced for energizing the negative ring relay 308 as follows: from ground at armature 318 and its resting contact, armature 317 and its working contact, and through the winding of negative ring relay 308 to battery. Relay 308, upon energizing, closes armature 335 without effect at this time and at armatures 338 and 341 completes the circuit for ringing the called subscriber as follows: from direct generator lead 75 10 extending from the transformer T in Fig. 2, working contact of armature 338 and said armature, negative ring conductor 187, armature 128, wiper 151 in engagement with the bank contacts terminating the negative line conductor of the 15 called subscriber, and thence over the negative line conductor through the substation ringer to ground. In case the subscriber's ringer should be bridged across both line conductors then the return circuit extends by way of the positive 20 line conductor, the connector bank contacts and wiper 154, armature 136, conductor 188, armature 341 and its working contact to generator return conductor 76 which is connected to the other terminal of the transmitter T shown in Fig. 2. 25 At armature 336 and 339 the ring-back condensers 337 and 340 are connected to the conductors 268 and 269 in order to transmit a ring-back tone to inform the operator that the actual ringing is taking place. At armature 342 relay 308 30 also connects ground to the lower winding of test relay 310 to ensure the energization of the latter and operates armature 343 to ground conductor 272 which is without effect at this time.

In case the called subscriber's number indicates that the called subscriber's ringer is connected to the positive line conductor and ground, then the control operator will operate the positive ring key in accordance with the code of the called subscriber. Responsive to the operation 40 of the positive ring key the positive side of the trunk conductor is opened a corresponding number of times to deenergize relays 303 and 304 and to energize differential relay 301. A circuit may now be traced for energizing the positive ring relay 309 as follows: from grounded armature 319 and its resting contact, armature 316, and through the winding of positive ring relay 309 to battery. Relay 309, upon energizing, at armature 348 connects direct generator to the positive 50 ring conductor 183 and thence by way of armature 136, wiper 154 in engagement with the bank contact terminating the positive line conductor of the called subscriber's line and thence through the called subscriber's ringer to ground, or if the ringer is bridged, to the negative line conductor and from thence to the negative bank contact terminating the negative line conductor, wiper 151, armature 128, conductor 187, armature 346, to the generator return conductor 76. At armatures 345 and 347 and their working contacts the ring-back condensers 337 and 340 are connected across the trunk conductors 268 and 269 for transmitting a ring-back tone to the control operator as previously described. At armature 349 relay 309 connects ground through the lower winding of test relay 310 and operates armatures 55 344 and 350 without effect at this time.

After the operator has operated the proper ringing key in accordance with the code of the called subscriber the operator may either operate her monitoring key or she may, without operating her monitoring key, take care of some of her other duties. In case the operator operates her monitor key MK the resistance R is inserted in 70 75

the positive trunk line conductor 453 with the result that the marginal relay 304 deenergizes while relay 303 is maintained in energized position. The differential relay 301 may or may not 5 energize in response to the inclusion of the resistance R in the positive trunk conductor but the energization of such relay at this time is without effect. Since the marginal relay 304 is now deenergized and the relay 303 is maintained in 10 energized position a circuit may now be traced for the monitor relay 307 as follows: from ground- 15 ed armature 309 and its resting contact, armature 321, armature 320, and through the winding of monitor relay 307 to battery. Monitor relay 307, upon energizing, at armatures 329 and 331 and 20 their resting contacts disconnects the negative and positive talk conductors extending back to the calling subscriber from the operator's trunk conductors 268 and 269 and connects the operator's 25 trunk conductors 268 and 269 to the line conductors of the called subscriber as follows: from negative trunk conductor 268, armature 329 and its working contact, negative ring conductor 187, armature 128, wiper 151 in engagement with 30 the bank contacts terminating the negative line conductor of the called subscriber's line, and trunk conductor 269 by way of armature 331 and its working contact, positive ring conductor 188, armature 136, and wiper 154 in engagement with 35 the bank contacts terminating the positive line conductor of the called subscriber's line. Monitor relay 307 at armature 332 opens a point in the circuit of busy relay 311 to deenergize the same in case it should be energized at this time 40 and operates armature 334 without effect at this time. By the operation of the monitor relay 307 the calling subscriber has therefore been disconnected and cannot listen in on the conversation between the control operator and the called subscriber when the called subscriber answers. 45 When the called subscriber answers the control operator will disconnect from the connection by restoring first the monitor key MK and the answer and dial key K.

In case the operator has other duties to perform she will not immediately operate her monitor key after having rung the code of the called subscriber and in this case a temporary talking and listening circuit is provided for enabling the calling and called subscribers to talk together over the following circuit: from the magneto telephone circuit indicated by the lower circle in Fig. 1, talking conductors 22 and 23 and armature 15, the associated bank contact and wipers 60 and 62 of the finder F, conductors 72 and 73, armatures 115 and 119, armatures 143 and 147 and their resting contacts, armatures 127 and 131, talking conductors 185 and 186, resting contacts of armatures 329 and 331 and said armatures, armatures 345 and 347 and their resting contacts, 55 over the dotted Y connection provided for bridge listening, armatures 352 and 354, resting contacts of armatures 338 and 341, conductors 187 and 188, armatures 128 and 139, wipers 151 and 154, and thence over the called subscriber's line. The 60 calling and called subscribers may converse over this temporary talking connection and when the operator comes in on the connection she will be advised of the fact that the called subscriber has answered due to their conversation since the 65 trunk conductors 268 and 269 are connected to the conductors 185 to 188, inclusive, at armatures 329 and 331. The operator may now disconnect by restoring the key K or if she desires to talk to the called subscriber to the exclusion 70

of the calling subscriber, she will operate the monitor key MK with the result that the talking connection extending to the calling subscriber is disconnected at armatures 329 and 331 as previously described. In case the bridged listening circuit is not required the dotted Y connection may be omitted and in such cases the operator will have to restore the monitor key MK in order to connect the calling and called subscribers together. When the control operator 10 restores the monitor key MK and the answer and dial key K, ground through the impulse springs of the calling device CD is disconnected from both conductors of the control trunk with the result that relays 302 303, and 304 now de- 15 energize. At armatures 318 and 319 relays 302 and 303 open the circuit of the slow-to-release relay 305 which after an interval deenergizes and at armature 322 disconnects ground from conductor 267 with the result that relay 207 in the distributor and relays 437 and 431 in Fig. 5 also de- 20 energize. At armature 323 and its working contact relay 305, upon deenergizing, disconnects ground from unlock conductor 78 to open the circuit to the vibrating relay 81 and also opens the circuit extending to the slow-to-release relay 306. Relay 305 at armature 323 transmits a ground impulse before the slow-release relay 306 deenergizes for energizing the cut-through relay 195 in the local connector as follows: from ground 25 by way of armature 323 and its resting contact, armature 325, armature 355 and its working contact, cut-through conductor 191, armature 131, and through the winding of cut-through relay 165 to battery. Relay 431, in Fig. 5, upon de- 30 energizing, at armatures 411 and 412 grounds conductors 268' and 269' to enable the second fifty-line unit to be connected with the trunk conductors 453 and 454 in a manner described for the system shown in the drawings. Relay 431, upon deenergizing, at armatures 434 to 436 connects up the supervisory switch and at armature 437 prepares the original energizing circuit for the signalling relay 439. Relay 237 in the distributor, upon deenergizing, prepares a point in the circuit extending to the motor magnet of the pre-selected finder; at armature 229 prepares a point in the circuit to the motor magnet 491 of the supervisory switch, at armature 232 opens the energizing circuit extending to signal relay 439 before relay 431 fully deenergizes and at the 40 resting contact of armature 232 prepares a point in the energizing circuit of relay 203. 45

Cut-through relay 105 in the local connector, upon energizing, at armature 140 completes a locking circuit for itself extending from grounded armature 112 and at the normally closed springs controlled by armature 140 opens the locking circuit of connecting relay 104 with the result that the latter relay now deenergizes. At armature 138 relay 105 connects the upper left-hand winding of the repeating coil RC to the negative talking conductor of the called subscriber's line; at armature 139 connects direct ground to the test wiper 152 to maintain the called subscriber's line busy to other connectors having access thereto; at armature 141 prepares a point in the circuit to slow-to-operate relay 162; and at armature 142 connects the positive talking conductor extending to the calling subscriber's line to the lower right-hand winding of the repeating coil RC thereby completing a talking connection between the calling and called subscribers exclusive of the common operating equipment shown in Fig. 4. The calling sub- 55 60 65 70 75

scriber is now bridged directly across the right-hand winding of the repeating coil RC while the called subscriber is bridged across the left-hand winding of the repeating coil RC. The deenergization of relay 104 at armatures 127 to 131, inclusive, disconnects the common equipment from the local connector and from the operator's control trunk.

In the common control equipment shown in Fig. 4 the slow-to-release relay 309 deenergizes after an interval and at armature 325 opens a point in the original energizing circuit to relay 105 which, however, is locked up at this time from grounded armature 112; at armature 326 and its working contact opens a point in the circuit extending to the start relay 170 of the ringing machine, and at its resting contact again grounds conductor 264. At armature 328 relay 306 prepares the original energizing circuit for relay 293 of the distributor and at armature 327 opens the locking circuits of relays 310, 312, and 313 which thereupon deenergize. By the deenergization of relays 310, 312, and 313 the common control equipment is completely released and may be used on a subsequent call.

After disconnecting, either subscriber may release the connection by turning the hand generator at his station. In case the calling subscriber, upon the termination of the conversation, operates his magneto, ringing current is transmitted over the previously traced talking circuit and through the right-hand winding of the repeating coil RC and through the winding of the alternating current relay 103. In a similar manner the operation of the magneto at the called substation will extend ringing current over the left-hand winding of the repeating coil RC and through the winding of the alternating current relay 107. The operation of alternating current relay 107 at armature 148 completes a circuit for energizing slow-to-operate relay 102 as follows: from ground by way of armature 141, armature 148, and through the winding of relay 102 to battery. The operation of alternating current relay 108 in a similar manner at armature 149 closes a circuit for relay 102. Relay 102 is made slow to operate to ensure that the relay will not operate from momentary surges of current on the line due to outside influences. Relay 102, upon energizing, at armature 113 closes a circuit for maintaining the hold relay 103 and the cut-through relay 105 in energized position and at armature 114 completes a circuit for grounding the supervisory release conductor 74 and for energizing slow-to-release relay 101. When the subscribers have finished ringing down the connection the alternating current relay 107 or 108 will deenergize and open the circuit of relay 102 and the latter relay after an interval of time will also deenergize and open the locking circuit of the hold relay 103 and the cut-through relay 105 as well as opening the circuit of relay 101. Since relay 101 is a slow-to-release relay ground is not connected to armature 112 until after the hold relay 103 and the cut-through relay 105 have fully restored. Hold relay 103, upon deenergizing, at armatures 115 and 119 opens the talking circuit, at armature 116 disconnects ground from the hold conductor 68 to remove the busy condition and to deenergize the cut-off relay 12 of the calling subscriber's line which thereupon deenergizes. At armature 117 slow relay 103 prepares a circuit for again grounding the chain conductor 69 as soon as the local connector restores its switch shaft and wipers to

normal position; and at armature 120 completes the circuit for energizing the release magnet 109. By the operation of the release magnet 109 the switch shaft and wipers are restored to their normal position in the well-known manner and the off-normal springs 122, 125, and 121 are likewise returned to their normal position or the position shown in the drawings. The off-normal springs 121 open the circuit to the release magnet 109, the off-normal springs 122 complete a circuit for grounding the chain conductor 69 and the off-normal spring 125 and its working contact removes the ground connection from the guard conductor 65 and at the working contact thereof prepares the circuit for again energizing the hold relay 103 and the connecting relay 104. The deenergization of cut-through relay 105 opens the talking circuit at armatures 138 and 142 and at armature 139 removes ground from the trunk wiper 152 to remove the busy condition from the called line to enable other connector switches to connect thereto. All of the relays in the local connector are now in their normal position or the position shown in the drawings and may therefore be used in subsequent calls.

Having described the detailed operations which take place when the called line is found to be idle, a description will now be given of the operations which take place when the control operator encounters a busy called line. For this purpose it will be remembered that the energization of relay 314 at armature 368 prepared a circuit to the busy relay 311 during the transmission of the second digit. In case the called line is busy then test wiper 152 in the local connector will encounter a grounded bank contact applied thereto by another connector either from armatures such as armatures 116 or 139 dependent upon whether the called subscriber originated the call or was called in the previous connection. A circuit may now be traced for the busy relay 311 as follows: from the grounded bank contact encountered by test wiper 152, armature 129, conductor 188, armature 368 and its working contact, armature 352, and through the winding of busy relay 311 to battery. At armature 360 busy relay 311 prepares a point in its own locking circuit and at armature 361 opens a point in the impulsing circuit. At armatures 358 and 359 busy relay 311 connects the busy tone to conductors 185 and 186 and from thence over the heavy talking conductors extending to both the calling subscriber and the control operator at the remote operating center. The busy tone circuit extends from the busy tone conductor, armature 362, armature 358, conductor 185, over the heavy talking conductors to the calling subscriber and over the conductors 268 and 269, through the repeating coils RC1 and RC2 to the control operator, while the busy tone return circuit returns to grounded armature 359. Shortly after the impulsing period the series relay 315 and relay 316 deenergize as previously described and the latter relay at the normally closed springs 65 controlled by armature 368 complete a locking circuit for the busy relay as follows: from grounded armature 327, armature 360, normally closed springs controlled by armature 368, armature 332, and through the winding of busy relay 311 to battery. When the operator hears the busy tone she will operate her monitor key MK to monitor the connection to determine if the called line is actually in use or if in a previous connection the subscribers have failed to ring 75

down the connection. Responsive to the operation of the monitor key MK, the resistance R is included in series with the positive trunk conductor with the result that the marginal relay 304 deenergizes as previously described. The de-energization of the marginal relay 304 completes the circuit for energizing the monitor relay 307 from grounded armature 369 by way of armatures 321 and 320. Monitor relay 307, upon energizing, at armature 332 opens the locking circuit of the busy relay 311 with the result that the busy relay at armatures 358 and 359 disconnect the busy tone from both the control operator and calling subscriber. At armatures 320 and 331 monitor relay 307 connects the trunk conductors 268 and 269 to the wipers 151 and 154 by way of conductors 187 and 193 and armatures 128 and 133. The operator's headset is now bridged across the previously established connection and in case the called line is actually in use the operator will hear the conversation and may inform the called subscriber that he is desired on a new connection if the call is urgent. If the call is not urgent the control operator will release the monitor key with the result that the monitor relay 307 deenergizes and again connects the operator to the calling subscriber so that the operator may inform the calling subscriber that the called line is busy. The calling subscriber will now hang up and the control operator now releases her answering and dial key K with the result that relays 302, 303, and 304 deenergize in the manner previously described. Relay 305 in the same manner as previously described deenergizes after an interval and transmits a release impulse for energizing relay 102 in the local connector over the following circuit: from grounded armature 323 and its resting contact, armature 325, armature 355 and its resting contact, conductor 198, armature 135, and through the winding of relay 102 to battery. The energization of relay 102 causes the energization of relay 101 after which the slow-to-release relay 306 deenergizes and opens the circuit of relay 102 with the result that the latter relay now deenergizes and opens the circuit of hold relay 103 and connecting relay 104. The de-energization of hold relay 103 causes the release of the local connector in the same manner as previously described. The de-energization of slow-to-release relay 306 also returns all the operated relays in the common equipment to their normal position ready for use in extending another call.

It will now be assumed that the called line is not actually in use but is marked busy due to the calling and called subscribers failing to ring down the local connection and therefore when the operator operates her monitor key and does not hear any conversation the operator will therefore challenge and in receiving no response will operate either one of her ring keys after restoring the monitor key in order to release the locked-up local connector. Responsive to the operation of either ringing key the negative ring relay 308 or the positive ring relay 309 will energize in the same manner as previously described to connect ringing current to either of the wipers 151 or 154. This ringing current will be extended from wipers 151 or 154 of the local connector now in use and from thence over the engaged bank contacts terminating the called line and from thence through the wipers corresponding to wipers 151 or 154 of the other called local connector and from thence through armatures corresponding to armatures

144 and 139, the upper left-hand winding of the repeating coil corresponding to RC, through the winding of the alternating current relay corresponding to relay 107, through the lower left-hand winding of the repeating coil, through corresponding armature 146 to the wiper corresponding to wiper 154, and thence back over the multiple bank contacts to wiper 154 of the local connector now in use. The alternating current relay in the held connector is thereupon energized by the ringing current and at the corresponding armature 148 completes a circuit by way of the corresponding grounded armature 141 for energizing the corresponding release relay 102 in the held connector. In the held connector relay 102 energizes the relay 101 and after termination of the ringing current the alternating current relay 107 and release relay 102 deenergize to unlock the hold relay such as relay 103 and the cut-through relay such as relay 105 in the held connector. The de-energization of the hold relay 103 in the held connector closes the circuit to the release magnet such as release magnet 109 whereupon the held connector is released in the same manner as previously described. The held connector is therefore released and removes the busy condition from both the calling and called subscribers at armatures such as armatures 116 and 139. In the common equipment shown in Fig. 4 the operation of negative ring relay 308 or positive ring relay 309 in addition to ringing down the held local connector establishes a circuit for energizing the test relay 310 through its lower winding at armatures 342 or 349. Relay 310, upon energizing, at armature 356 establishes the previously traced locking circuit therefor. The local connector and the common equipment are now in the same condition as if the local connector had encountered an idle line instead of a busy line and therefore the operation from this point on is just the same as previously described in connection with the local connector encountering an idle called line. The operator will therefore operate the proper ringing key in accordance with the code of the called subscriber and when the called subscriber answers the operator will restore her answer and dial key K in order to directly connect the calling and called subscribers together and in order to release the common control equipment in Fig. 4 to permit the control equipment and the control trunk to be used in establishing a new connection.

In case the calling subscriber has asked to be connected with a toll operator, then the first digit dialled by the control operator raises the wipers of the toll connector to a toll level whereupon the toll normal post springs PS1 are operated. The operations performed by both the calling subscriber and the control operator are the same as those previously described. The operation of the normal post springs PS1 at springs 156 prepares a point in the circuit for directly operating the rotary magnet 110 in a manner to be more fully described hereinafter. The operation of springs 157 prepares a point in the circuit for relay 106. The operator now dials the second digit assigned to the toll trunk whereupon the local connector rotates its wipers in the same manner as previously described. The wipers of the local connector have now been rotated into engagement with the bank contacts terminating the first toll trunk in the group and in case this first toll trunk is busy test wiper 152 will engage a grounded bank contact with the result that the busy relay 311 will energize

in the same manner as previously described to transmit a busy tone to the control operator. In case more than one toll trunk is provided the operator, upon hearing the busy tone, will then 5 dial the digit 1 to set the wipers of the local connector into engagement with the next toll trunk as follows: responsive to the operation of the calling device CD at the remote operating center for the digit 1 a single impulse is transmitted over the trunk line to cause the line relay 302 to momentarily deenergize, at which 10 time a circuit may be traced from grounded armature 312, armature 317 and its resting contact, armature 324, armature 357, armature 366, conductor 163, armature 123, springs 156 of the operated normal post springs PS1, and through the rotary magnet 110 to battery. By the operation of the rotary magnet 110 the wipers 151 to 154, inclusive, are stepped into engagement with the 15 next toll trunk. In case this toll trunk is likewise busy the wiper 152 will again encounter ground. The impulse transmitted to the rotary magnet by way of the normal post springs 156 also extends by way of armature 134, conductor 195, working contact at armature 364, and through the winding of series relay 315 to battery for energizing the latter relay. Series relay 315 at armature 369 again energizes relay 314 which at armature 368 opens the locking 20 circuit of the busy relay which thereupon deenergizes and disconnects the busy tone from the control operator. In case the second toll trunk is busy wiper 152 will again encounter a 25 grounded bank contact with the result that the busy relay will again be energized to again transmit the busy tone to the control operator. In case, however, the second toll trunk is idle, then there will be no ground connection encountered by wiper 152 with the result that the busy relay 30 will not at this time reenergize. Instead, however, a circuit may be traced for energizing the 30 test relay 310 as follows: from grounded armature 327, upper winding of test relay 310, resting contacts of armature 368 and said armature, conductor 163, armature 129, test wiper 152, the 35 idle test terminal terminating the toll trunk, in this case conductor 162, contacts of busy key in the toll connector, and through the resistance 833 to negative battery. Test relay 310, upon 40 energizing, at armature 355 prepares a point in the circuit for the cut-through relay 105, at armature 356 again completes its locking circuit and at armature 357 opens a point in the impulsive 45 circuit to the local connector.

50 When the operator fails to hear the busy tone after dialling she knows that she has been connected to an idle toll trunk and therefore operates either one of her ringing keys to operate the negative ring relay 308 or positive ring relay 309 in the same manner as previously. In the same 55 manner as previously described ringing current is connected to the wipers 151 and 154 and extends from thence over conductors 161 and 164 to the toll connector shown in Fig. 9. The ringing current is transmitted through the right-hand winding of the repeating coil and through the alternating current relay 804 in the toll connector whereupon the relay 804 energizes and at armature 828 completes a circuit for energizing 60 ringing relay 803. Ringing current is now transmitted from direct generator to the resting contact of armature 822 and said armature, working contact of armature 825 and said armature, toll trunk conductor 715, through the right-hand winding of the repeating coil in Fig. 8, conductor 65

716, armature 827 and its working contact, and to the generator return conductor. Ringing current is induced from the right-hand winding of the repeating coil in Fig. 8 into the left-hand winding whereupon the drop D is operated to 70 signal the toll operator of an incoming call. The toll operator, upon answering the call, inserts her cord circuit into the jack J, thereby disconnecting the buzzer 704 at jack springs 701 and at jack springs 702 disconnects the drop D, after 75 which the toll operator operates the hold key K. Responsive to the operation of hold key K, springs 705 complete the talking circuit; springs 706 prepare a point in the circuit for the buzzer 704 and at springs 707 connect ground through 80 the impedance 708 through the normally closed springs controlled by dial key springs 709 and 710 to the toll trunk conductors 715 and 716 by way of the upper right-hand and lower right-hand windings of the repeating coil. This ground 85 connection extends over the negative toll trunk conductor 715 by way of armature 825 and its resting contact, upper left-hand winding of the repeating coil in the toll connector, through the upper winding of the differential relay 806, and 90 through the winding of line relay 807 to battery. In a like manner ground is connected over the toll trunk conductor 716 by way of armature 827 and its resting contact, through the lower left-hand winding of the repeating coil in the toll connector, through the lower winding of differential relay 806, through the winding of relay 808, and through the winding of marginal relay 809 to battery. Relays 807, 808, and 809 95 energize over the above-traced circuits but the differential relay due to its opposed windings does not at this time energize. Line relay 807, upon energizing, at armature 834 completes an obvious circuit for energizing relay 810, which relay thereupon energizes and at armature 839 connects direct ground to conductor 162 by way of the busy key 830 to maintain the toll trunk busy to local connectors having access thereto. At armature 840 relay 810 prepares a point in the 100 circuit for relay 801, at armature 841 prepares a point in the impulsive circuit and at armature 842 opens a point in the circuit extending to the release magnet 817. Relay 803, upon energizing, at armature 836 closes an auxiliary circuit for release relay 810 and at armature 835 prepares a point in the circuit for energizing relay 802 which is not energized at this time because the marginal relay 809 is likewise energized and has at armature 837 opened the circuit to relay 802.

105 The control operator after ringing the toll operator operates her monitor key MK in order to converse with the toll operator. When the toll operator answers the control operator may inform the toll operator that the calling subscriber desires a particular toll connection and may thereafter release her monitor key in order to connect the calling subscriber directly with the toll operator. During the time the monitor relay 807 is in energized position the talking circuit between the two operators extends from the control operator to the wipers 151 and 154 as 110 previously described over conductors 161 and 164, armatures 821 and 819 and their resting contacts and through the right-hand windings of the repeating coil in the toll connector and thence through the left-hand windings of the repeating coil at armatures 825 and 827 over the toll trunk conductors 715 and 716, through the right-hand windings of the repeating coil in the toll trunk 115 TT and from thence through the left-hand wind- 120

ings of the repeating coil in the toll trunk TT through the hold key springs 705 to the tip and ring springs 701 and 702 of jack J and through the tip and ring of the operator's cord circuit to her headset. When the control operator restores her monitor key MK and thereby deenergizes the monitor relay 367 the calling subscriber is connected to both the toll operator and control operator through the resting contacts of armatures 329 and 331, armatures 345 and 347, armatures 352 and 354, and armatures 333 and 341 and their resting contacts. The control operator may now retire from the connection and in doing so restores her key K whereupon the relays 302, 303, and 304 and later on relays 305 and 306 deenergize to cause the common equipment in Fig. 4 to be released from the local connector in the same manner as previously described. An impulse of current is transmitted to the local connector to cause the energization of cut-through relay 103 in the same manner as previously described, whereupon the calling subscriber is connected directly to the toll operator independent of any connections in the common equipment. This circuit is the same as that described in the connection between two local subscribers wherein the calling subscriber is connected to the right-hand winding of the repeating coil RC and the toll operator is connected to the left-hand winding of the repeating coil RC in the local connector. After conversation the calling subscriber may ring down the local connector in the same manner as previously described or the toll operator may also ring down the local connector as follows: the operator will therefore operate the dial key K, thereby substituting the ground through the impulse springs 712 of the calling device CD for the ground through the impedance 708 and springs 707 and thereafter operates the ringing key RK; whereupon ground is removed from the positive trunk conductor 116 to cause the operation of differential relay 303 and the deenergization of relays 300 and 309. Relay 303, upon deenergizing, at armature 336 and its resting contact completes a circuit by way of armature 331 for energizing relays 305 and 301 in parallel to battery. Relay 305 at armature 329 short circuits the alternating current relay 304 to prevent its operation at this time while relay 301 at armatures 321 and 318 connects direct generator by way of resting contact of armature 322 and said armature, working contact of armature 321 and said armature to conductor 151, through the wiper 154, armature 144, armature 138, through the left-hand windings of the repeating coil RC and alternating current relay 107, armature 146, wiper 154, conductor 104, armature 318 and its working contact, armature 323 and its resting contact, to generator return. The alternating current relay 107 in the local connector is energized over this circuit to cause the energization of relay 102 to release the local connector in the same manner as previously described. The toll operator thereafter releases the hold key HK and dial key DK to remove ground from conductors 715 and 716 whereupon the relays 307, 308, and 309 deenergize. The deenergization of relays 307 and 308 opens the circuit of relay 310 which releases after an interval of time and at armature 239 disconnects ground from conductor 102 to make the toll connector accessible to other local connectors. In case the operator should remove her cord circuit from the jack J without restoring the hold key HK a circuit would be completed for the

buzzer 704 in order to call the operator's attention to the fact that she has failed to restore the hold key HK. This circuit may be traced from the positive pole of the dry cells DC through the two left-hand windings of the repeating coil, through the springs 705 of the hold key HK, through the jack springs 701, through the winding of buzzer 704 and its interrupting contact, and through the hold key springs 706 to the other pole of battery. The buzzer 704 operates over 10 the above-traced circuit until the toll operator restores the hold key HK.

There are two ways in which reverte calls may be made, one in which the calling subscriber asks the control operator to ring back 15 on the subscriber's line to complete the desired connection and the other in which the calling subscriber may ring the code of the called subscriber located on his line by operating the magneto at the calling substation in accordance with 20 the called subscriber's code. In case the calling subscriber desires that the control operator complete the call to a station on his own line, the calling subscriber will initiate the call in the same manner as previously described and when 25 the control operator answers in response to the signal the operator will therefore inform the calling subscriber to replace his receiver whereupon the control operator operates the proper ringing key in accordance with the code of the called 30 subscriber without dialling any digit. The finder F, the distributor, and the relays 103 and 104 are energized in the same manner as previously described. In response to the operation of either ringing key relay 308 or 309 is energized to transmit ringing current back over the calling line and at armature 342 or 340 completes a circuit for energizing the lower winding of the test relay 310 which thereupon energizes and at armature 355 opens a point in the release circuit and at 40 its resting contact prepares a point in the cut-through circuit extending to the relay 105. By the operation of either ringing relay 308 or 309 direct generator from conductor 75 is connected to either ring conductor 107 or 108. The operation of either ringing relay 308 or 309 at either 45 armature 335 or 344 completes a circuit for energizing the reverting relay 106 since the relay 312 is not energized at this time due to the fact that no dialling has taken place. The circuit for energizing the reverting relay 106 may be traced 50 as follows: from ground by way of armature 321, armature 363 and its resting contact, either armature 344 or armature 335, conductor 102, armature 103, and through the winding of reverting relay 106 to battery. Reverting relay 106 therefore energizes each time either of the ringing relays is operated and such reverting relay at armatures 103 and 107 connects the ringing conductors 107 and 108 to the calling subscriber's 55 line by way of armatures 115 and 119. Ringing current is therefore transmitted over the calling line in accordance with the code of the called subscriber. After ringing the code of the called subscriber both the calling and called subscribers thereafter remove their receivers and may converse with each other in the usual manner. The control operator now disconnects from the connection by restoring her key K to cause the operation of the cut-through relay 105 over the circuit as previously traced. The hold relay 103 and the cut-through relay 105 are held in operated position during conversation and the hold relay 103 at armature 116 maintains the calling and called lines busy to the finders and connectors having access thereto. After conversation 70 75

- either the calling or called subscriber may ring manner previously described and at armature 47 down the connection by operating the alternating current relay 108 which in turn causes the energization of release relay 102 to deenergize 5 and restore the relays in the local connector to normal position. In this type of reverting call it is therefore seen that the hold relay 103 at armature 116 maintains the line busy during conversation.
- 10 In case the calling subscriber desires to make his own reverting call and therefore operates the hand generator in accordance with the code of the called subscriber, the operator, however, is signalled in the same manner as previously described and when the operator comes in on the control trunk and either hears the calling subscriber ringing the code of the called subscriber or is advised by the calling subscriber that he is making his own reverting call the control 15 operator will disconnect from the connection by restoring the key K without ringing. Since the control operator did not ring over the control trunk neither of the ringing relays 308 or 309 have therefore been energized and therefore the 20 test relay 310 is not energized. In this case and at a time when the operator disconnects by the restoration of the key K an impulse of current is transmitted by the two slow-acting relays 305 and 306 for operating the release relay 102 in the 25 local connector as follows: from ground by way of armature 323 and its resting contact, armature 325, armature 355 and its resting contact, release conductor 196, armature 135, and through the winding of release relay 102 to battery. The 30 release relay 102 is operated for the interval of time it takes slow-to-release relay 306 to de-energize after which the impulse is terminated and relay 102 likewise deenergizes. Relay 102 in the same manner as previously described operates the slow-to-release relay 101 and after relay 102 itself deenergizes ground is removed from the holding windings of hold relays 103 and 104 with the result that these relays deenergize. The deenergization of connecting relay 104 disconnects the common equipment from the local 35 connector while the deenergization of hold relay 103 removes ground at armature 116 from the hold conductor 58 whereupon the calling and called lines are no longer marked busy in the 40 banks of the finder or local connector. The disconnection of ground from conductor 68 also opens the circuit to the cut-off relay 12 with the result that the cut-off relay 12 now deenergizes and restores the line circuit LC to its normal 45 position. The calling and called subscribers, however, talk over their lines in the usual manner.
- 50 The case will now be considered where the calling subscriber is a paystation subscriber. In this case the line circuit LC1 is identical with the line circuit LC with the exception that the paystation tone relay group PST is connected to such paystation line. In this case when a paystation line originates a call by the operation of the hand generator thereat the line relay 31 is energized by ringing current extending over the calling subscriber's line and through the upper winding of line relay 31. Relay 31 in addition to closing a locking circuit through its lower winding also completes a circuit through the resistance 42 for energizing the tone connecting relay 43 in the paystation relay group PST. At armature 46 relay 43 prepares a point in the circuit for connecting the tone generated by the differential relay 45 which is energized in the 55 60 65 70 75
- completes a locking circuit for itself extending from grounded armature 48. The connecting relay 43 is energized in series with the finder start relay 201 in the distributor in parallel with the lower winding of line relay 31. When the start relay 170 in the ringing machine operated said relay at armature 174 grounds conductor 78 to operate the differential relay 45 as previously described. The vibrating relay 81, it will be remembered, is energized as soon as the relay 305 in the common equipment energizes in response to the control operator answering the call. The relay 81 operates its vibrating armature 80 which continues to vibrate for a predetermined length 10 of time after which it closes the circuit to the slow-to-operate relay 45 which therefore energizes and at armature 48 opens the locking circuit of the tone connecting relay 43 so that the relay 43 will disconnect the tone from the calling line a period of time after the control operator has answered and has heard the paystation tone. The remainder of the connections are established in the same manner as previously described for other substation lines.
- 15 20 25 30 35 40 45 50 55 60 65 70 75
- Since the trunk lines to distant manual exchanges terminate in line circuits which are identical with the line circuit shown in LC, the calls to and from such distant manual exchanges are handled in exactly the same manner as described for local subscribers. In some cases there may be more than one trunk to the same distant manual exchange and in this case when the control operator operates the local connector to the level in which said trunk lines terminate 30 then the trunk normal post springs PS2 are operated to prepare a circuit for the rotary magnet 110 so that the control operator, after dialling the second digit of the called number, may dial the digit 1 in case the first trunk is busy in order 35 to step the local connector another step into engagement with the second trunk line in case the first trunk line should be busy. It may be noted that the normal post springs 155 are connected in parallel with the normal post springs 156. The circuit for rotating the local connector a step at a time over the trunk line is the same as that traced through the normal post springs 156 in establishing the connection to an idle toll trunk.
- 40 45 50 55 60 65 70 75
- Referring now to the distributor, a faulty condition will now be considered in which a finder fails to cut through and establish connection to the calling subscriber. It will be remembered that the relay 203 energized and at armature 222 completed a circuit for energizing the vibrating relay 205 which at the vibrating armature 226 prepared a circuit for relay 204. Relay 204 due to its slow-to-energize characteristic will not operate during the time the vibrating armature 226 is operating and therefore relay 204 in the normal course of connections is never operated. However, in case a finder fails to cut through a sufficient time will elapse to permit the operation of relay 204 which at armature 224 therefore closes a circuit for energizing the distributor motor magnet 253. Motor magnet 253, upon energizing, at its interrupter springs 254 opens the circuit of relay 203 which thereupon deenergizes and at armature 222 opens the circuit to the vibrating relay 205. Relay 205 deenergizes 70 and in turn deenergizes relay 204 with the result that the latter relay opens the circuit to magnet 253 which thereupon deenergizes and steps the wipers of the distributor into engagement with the next bank contact terminating the next 75

finder connector link. From this point on the searching arrangement for the distributor to select an idle finder connector link is the same as previously described.

- 5 In case a fuse blows, the charger fails, or the connector fails to release properly a relay group not shown is arranged to ground the trouble conductor 236 in the well-known manner customary in automatic telephone systems. When 10 conductor 236 is grounded, slow-to-operate relay 240 is energized by way of armature 240 to cause a signal to be transmitted over the control trunk to the control operator. Slow-to-energize relay 241, upon energizing, at armatures 243 and 244 15 prepares a point in the circuit for connecting direct generator to the trunk conductors 263 and 269; at armature 245 opens a point in the circuit for extending to relay 263; and at armature 246 completes a circuit for energizing relay 211 as 20 follows: from ground by way of grounded armature 414 in Fig. 5, conductor 262, armature 232 and its resting contact, conductor 213, armature 323, conductor 274, armature 246, and through the upper winding of relay 211 to battery. Relay 211, upon energizing, at armature 249 prepares a 25 point in the circuit for energizing relay 209; at armature 250 completes an obvious locking circuit from grounded armature 241 through its lower winding; and at armature 251 completes a 30 circuit for energizing relay 207 and relay 407 over conductor 264. At armatures 247 and 248 relay 211 connects direct generator from conductor 75 through the condenser 252, working contact of armature 244 and said armature, 35 armature 248 to conductor 263 and from generator return conductor 75 through armatures 243 and 247 to conductor 269 and from thence through the repeating coil RC1 over the trunk conductors extending to the remote operating 40 center to the repeating coil RC2 and thence over the heavy talking conductors to the operator's headset. Relay 407 in the unit switching arrangement energizes to prevent the second unit from seizing the control trunk at this time in 45 the same manner as previously described. Relay 207, upon energizing, at armature 229 opens a point in the stepping circuit extending to the motor magnet 401 of the supervisory switch; at armature 231 locks up to the grounded conductor 50 264; and at armature 232 completes a circuit for energizing the signal relay 430 in Fig. 5 as previously described. Relay 430, upon energizing, at armature 433 operates relay 431 and at armatures 432 and 434 momentarily connects ground 55 and negative battery to the trunk conductor extending to the operating center in order to operate the drop at the operator's position to signal the operator in the same manner as previously described. The control operator now answers by 60 operating the key K and hears the tone connected to the trunk conductors by relays 210 and 211 thereby indicating to her that some trouble has occurred in the remote exchange. Responsive to the operation of the key K the relays 302, 303, 65 and 304 are energized in the same manner as previously described after which the relays 305 and 306 are likewise energized. Relay 305, upon energizing, at armature 322 grounds conductor 267 to hold relay 431 in energized position which 70 latter relay at armature 439 grounds conductor 264. After hearing the steady generator tone indicating trouble, the control operator will thereupon release the key K whereupon the relays 302, 303, and 304 will deenergize. Relay 302, 75 upon deenergizing, at armature 318 completes a

circuit for energizing relay 209 in the distributor as follows: from ground by way of armature 317 and its resting contact, armature 317 and its resting contact, armature 324, conductor 275, armature 249, and through the winding of relay 209 to battery. Relay 209, upon energizing, at armature 239 completes a locking circuit for itself to the grounded trouble conductor 236; at armature 240 opens the circuit of relay 210 which thereupon deenergizes; at armature 241 opens the 10 locking circuit of relay 211 which likewise deenergizes. Relay 210, upon deenergizing, at armatures 243 and 244 removes the tone connection from the trunk conductors 263 and 269; at armature 245 reestablishes the circuit for relay 209 and at armature 246 opens a point in the original energizing circuit of relay 211. Relay 211, upon deenergizing, at armatures 247 and 248 likewise opens a point in the tone circuit; at armature 249 opens a point in the original energizing circuit of relay 209 which is now held locked over the conductor 236; at armature 250 opens a point in its own locking circuit; and at armature 251 disconnects one of the ground connections to conductor 236. 15 20 25

In the common equipment the slow-to-release relay 305, upon deenergizing, at armature 322 disconnects ground from conductor 267 to unlock relays 207, 407, and 431 before slow-to-release relay 306 deenergizes and places ground 30 on conductor 264 at armature 326. Relays 407 and 431 now deenergize as described before and relay 207, upon deenergizing, reestablishes the impulsive circuit to the supervisory motor magnet 401. 35

The operator now reoperates her key K with the result that relays 302, 303, and 304 and later on relays 305 and 306 are energized as previously described. Since the relay 431 is not operated at this time the control operator's trunk is therefore connected directly to the supervisory switch shown in Fig. 5. It should probably be mentioned at this time that the tone conductor 499 in Fig. 5 is connected to a tone relay group in the power supervisory circuit and that interrupter generator tone is normally connected thereto in case no trouble has occurred. This relay group (not shown) is arranged to connect steady generator tone to the tone conductor 499 during non-emergency alarm conditions such as 45 when a connector fails to properly release and is also arranged to disconnect all tone connections from the tone conductor 499 during an emergency alarm condition such as when one or more of the fuses blow. 50 55 60

As previously described, the control operator after answering the alarm signal by the operation of the key K hears the alarm signal after which she restores the key K and again reoperates the key K to connect her trunk directly to the supervisory switch. The control operator, in the case where only one fifty-line unit is used, hears steady generator in case of a non-emergency alarm, hears no tone in case of an emergency alarm, and when no trouble has occurred 65 hears interrupter generator tone. The tone circuit extends by way of the tone conductor 499, normal bank contact engaged by wiper 405 and said wiper, armature 438, through the right-hand windings of the repeating coil RC1 to armature 70 436, wiper 406 in engagement with its normal bank contact terminating the generator return conductor 75. In the well-known manner the tone is induced into the left-hand windings of the repeating coil RC1 and extends over the con- 75

ductor to the remote operating center and through the repeating coil RC2 to the operator's headset. In the case where two fifty-line units are used then the operator must first determine 5 which of the two units is in trouble. In this case the operator will dial a predetermined digit to directively operate the supervisory switch to engage a certain contact. In one unit a tone is connected to this certain contact while in the other no tone is connected thereto and therefore the operator will know which unit she is connected to dependent upon whether she hears a tone or not. This arrangement is accomplished by omitting the Z-Z wiring shown in Fig. 5 from the wiring of the supervisory banks in one of the units. The dialling circuit for stepping the supervisory switch is as follows: from grounded armature 318 and its resting contact, armature 317 and its resting contact, armature 324, conductor 275, armature 229, conductor 265, and through the winding of motor magnet 401 to battery. The operation of the motor magnet 401 steps the wipers in response to the impulses into engagement with the predetermined contacts 20 to enable the control operator to determine which of the two fifty-line units she is connected to. After the operator has determined which unit the trouble is located in the control operator will restore the key K in order to release the supervisory switch. This circuit may be traced as follows: when the control operator restores the key K the relays 302 to 305, inclusive, in the common equipment deenergize as previously described, and relay 305 at armature 322 connects ground to conductor 265 and from thence through the multiple bank contacts accessible to wiper 403 in the supervisory switch and through the interrupter springs 402 of the motor magnet 401 and through the winding of motor magnet 401 to battery. The motor magnet 401, upon energizing, at its interrupter springs 402 interrupts its own stepping circuit to step the wipers into engagement with the next bank contact. As long as wiper 403 engages grounded bank contacts the motor magnet 401 operates in the manner of a buzzer to return the wipers of the supervisory switch to their normal positions or the positions shown in the drawings.

Another alarm condition may arise when all of 50 the local connectors are busy either due to such connectors being actually in use or due to the local subscribers failing to release the same after disconnection. The all-trunks-busy relay 208 is normally energized over the chain conductor 69 which extends to all of the local connectors and is connected to ground by way of the off-normal springs 122, armature 117, and springs 124 of the busy key in all the local connectors. When all of the local connectors are busy all of the ground connections are disconnected from conductor 69 with the result that the all-trunks-busy relay 208 deenergizes. Relay 208, upon deenergizing, at armature 237 completes a circuit for energizing relay 211 as follows: from grounded armature 414 in Fig. 5, conductor 262, armature 232 and its resting contact, conductor 273, armature 328, conductor 274, armature 237 and its resting contact, armature 242, and through the upper winding of relay 211 to battery. At armature 234 all-trunks-busy relay 208 prepares a circuit for connecting busy tone to the control trunk and at armature 235 prepares a point in the locking circuit for relay 209. Relay 211, upon energizing, at armatures 247 and 248 connects the busy tone to the control trunk as follows: from busy tone conductor 233, armature 234, armature 244, armature 248, to trunk conductor 268, and thence over the control trunk through the repeating coils as previously described and back over conductor 269, armature 247, and armature 243 and its resting contact to ground. The busy tone is induced through the repeating coils in the control trunk which informs the control operator that all of the local connectors are marked busy and are unavailable to extend further connections. At armature 249 relay 211 prepares a point in the energizing circuit of relay 209, at armature 250 completes a locking circuit through its lower winding, and at armature 251 completes the previously traced circuit for energizing relays 207 and 407. Relay 407 energizes to prevent the other unit from seizing the control trunk while relay 207 upon energizing at armature 231 locks as before and at armature 232 completes the previously traced circuit for energizing the signal relay 430 in Fig. 5. Responsive to the operation of the signal relay 430 the control operator is signalled in the same manner as previously described, after which the relay 431 is likewise energized to open the circuit of the signal relay 430. When the operator observes the operation of the drop she will answer the call by operating her answer key K. The relays 302, 304, 303, 305, and 306 in the common equipment operate in the same manner as previously described and in this case since the busy tone is connected to the control trunk the operator hears the same and is informed that all of the local connectors are busy. The operator therefore restores the key K with the result that an impulse of current is transmitted to relay 209 over the circuit previously described. Relay 209, upon energizing, at armature 241 opens the locking circuit of relay 211, at armature 242 opens a point in the original energizing circuit of relay 211, and at armature 238 completes a locking circuit for itself at grounded armature 235. Relay 211, upon deenergizing, at armatures 247 and 248 disconnects the busy tone from the control trunk. The control operator now reoperates the key K and is again connected directly to the supervisory switch in the same manner as previously described. In order to supervise the local connectors the control operator now dials the digit 1 to set the wipers of the supervisory switch into engagement with the bank contacts terminating the first local connector. When line relay 302 is deenergized responsive to this impulse a circuit is closed by way of armatures 318, 317, 324, conductor 275, armature 229 of relay 201 which deenergizes responsive to the deenergization of relay 211, conductor 265, and through the winding of motor magnet 401 to battery. The wipers of the supervisory switch are now operated into engagement with their first set of bank contacts; wiper 404 being connected to conductor 74, wiper 405 being connected to conductor 72, and wiper 406 being connected to conductor 73. Since the relay 431 is not energized at this time the control trunk is bridged directly across the talking conductors of the first local connector by way of armatures 435 and 436. The operator can now hear if any conversation is taking place and in case she does not hear any conversation she will challenge and if no response is given to her challenge she will operate either of the ringing keys. Responsive to the operation of either ringing key either the ringing relay 309 or 308 will be operated to ground conductors 272 at armatures 343 or 350. A circuit can now be traced over the grounded con-

- ductor 272 by way of wiper 404 in engagement with the bank contacts terminating the first local connector, conductor 74, and thence through the winding of slow-to-release relay 101 to battery.
- 5 Relay 101 energizes over the above-traced circuit and at armature 112 opens the locking circuit of relays 103 and 105 with the result that these latter relays release. The deenergization of relays 103 and 105 causes the first local connector 10 to release in the same manner as previously described and also removes the busy condition from the calling and called subscribers' lines to enable said subscribers to be called. As soon as this local connector is released to normal position the 15 off-normal springs 122 are closed with the result that ground is again connected to the conductor 69 and relay 203 is again energized. The energization of the all-trunks-busy relay 203 at this time opens the locking circuit of relay 209 which 20 deenergizes and therefore restores the distributor circuit to normal position ready to receive additional calls. In order to supervise the second local connection the operator will again dial the digit 1 whereupon the wipers of the supervisory 25 switch in Fig. 5 are stepped into engagement with the terminals terminating the conductors extending to the second local connector. The operator challenges if she does not hear any conversation and will release such connection in the same 30 manner as previously described. The operator therefore can monitor all of the local connectors and will release all such connectors which are not actually in use. From the foregoing it will also be appreciated that the operator need not 35 wait for an all-trunks-busy tone to indicate that all of the local trunks are busy but at any time may come in on the control trunk and operate the supervisory switch as just described to supervise all of the local connectors and release those which 40 are not actually in use.
- In some instances the control operator may 45 initiate a call either for testing purposes or for connecting to a certain called subscriber. In order to do this the operator will operate her key K at a time when the control trunk is idle after which she will operate either ringing key momentarily. Relays 302 to 306, inclusive, operate in the same manner as previously described and in response to the operation of the ringing key 50 either ringing relay 308 or 309 energizes to ground conductor 272, whereupon a circuit may be traced from grounded conductor 272 by way of wiper 404 in engagement with its normal bank contact, armature 434, conductor 74, armature 56 in Fig. 1, through the upper winding of line relay 51, and through armature 55 and resistance to battery. Line relay 51 is energized over the above-traced circuit and at armature 54 completes a locking circuit for itself including the finder start 55 conductor 39 and at armature 53 prepares a circuit for the cut-off relay 52. The operator now releases the key K with the result that the relays 302 to 306 in the common equipment de-energize as previously described. Due to the operation of line relay 51, in Fig. 1, and the disconnection of the control operator from the control trunk, the condition is now identical with a calling subscriber initiating a call and operating his individual line relay. The line relay 51 therefore 60 locks through its lower winding in series with the start relay 201 in the distributor and the operator is now therefore signalled the same as a calling subscriber initiating a call in the same manner as previously described. When the control operator 65 answers she will thereupon dial the local 70 75

connector to the bank contacts of the desired called subscriber and ring the same in the same manner as previously described, and after conversation she will release from the trunk in the same manner already described.

5 The emergency operating set indicated by the square in Fig. 5 is provided so that a local operator if desired may complete the calls in the same manner as described for the remote operator. This emergency operating set is practically identical with the control operator's set shown in the remote operating center and therefore the local operator would complete the connections in the same manner as described for the remote operator.

10 Having described the detailed circuit operation which takes place over a two-wire metallic control trunk, a description of the modification shown in Figs. 6 and 7 will be given of the operation which takes place over a control trunk comprising only a single conductor. This single conductor may be phantomed out of an existing toll trunk, if desired. Fig. 6 is somewhat similar to Fig. 4 and has been modified somewhat to permit a call over a single conductor. In a like 15 manner Fig. 7 is somewhat similar to Fig. 5 and has also been modified to permit control over the single conductor. As far as possible the same numbering arrangement has been applied to the similar parts in the similar figures, that is, as an 20 example, the ringing relays in both figures have been designated by somewhat similar reference characters such as ringing relays 308 and 309 in Fig. 4 which correspond to the ringing relays 308 and 309 in Fig. 6. Figs. 6 and 7 are to be substituted for Figs. 4 and 5 and it will be noticed that the conductors extending between the drawings are arranged to permit such substitution. The conductors extending in Figs. 6 and 7, however, have been primed—for example, 185 in 25 Fig. 2 now extends and connects with conductor 185' in Fig. 6. Figs. 1, 2, and 3 have been explained in detail and since there is no change in the detail operations thereof when used in connection with Figs. 6 and 7, only a brief résumé of 30 their operations will be given in connection with the detail explanation of Figs. 6 and 7. In the first explanation of this modification divided ringing is to be provided and therefore Fig. 10 is to be connected as indicated in Fig. 6, while in 35 Fig. 6 the dotted Z connections are to be omitted. When a single control conductor is used a special 40 means of signalling arrangement must be provided and therefore a very high resistance relay such as relay 678 in the remote operating center 45 is normally energized over the control conductor. This circuit may be traced as follows: ground through the high-resistance winding of relay 678, armature 676, normally closed springs controlled by armature 670, through the right-hand windings of the repeating coil RC4, over the single conductor 690 to the local exchange through the resting contact of armature 633 and said armature, armature 632, through the left-hand windings of the repeating coil RC3, conductor 270', conductor 270, to conductor 270' of Fig. 6, through the windings of relays 501, 504, through the normally closed springs controlled by armature 588 and 55 through the lower winding of impulsing relay 502 to battery. The high-resistance relay 678 alone is energized over this circuit and the relays in the common equipment shown in Fig. 6 are not energized on account of the high resistance of relay 678. When a local subscriber 60 initiates a call the local subscriber operates his 65 70 75

hand generator and energizes his associated line relay to lock up in the same manner as previously described. Relay 201 in the distributor is energized over the circuit previously traced thereby causing the operation of the distributor and finder switch in the same manner as previously described. The finder now operates in search of the calling line and operates the stepping relay 206 in the distributor and when the finder finds the calling line the relay 207 is energized in series with the stepping relay 206 as previously described. Responsive to the operation of relay 207 the hold relay 103 and the connecting relay 104 in the local connector energize as previously described, and at armature 232 relay 207 completes a circuit for energizing the signal relay 630 as follows: from grounded armature 232, to conductor 263 and from thence by way of conductor 263', normally closed contacts controlled by armature 631, and through the winding of signal relay 630 to battery. Relay 630, upon energizing, at armature 633 closes a circuit for energizing the slow-to-operate relay 631 and at armature 632 opens the circuit extending over the single control conductor 600 in order to deenergize the high-resistance relay 678 at the remote operating center. After a short interval relay 631 energizes and at armature 637 opens the circuit of the signal relay which thereupon deenergizes after a short interval. Relay 631 at armatures 638 and 639 completes a locking circuit for itself by way of grounded conductors 264' and 267'. The deenergization of the high-resistance relay 678 at the remote operating center closes a circuit for relay 676 by way of armatures 669 and 671. Relay 676, upon energizing, at armature 675 completes a locking circuit for itself; at armature 676 opens another point in the circuit of the high-resistance relay 678 to prevent its reenergization when the signal relay 630 is restored to normal to close the control trunk at armature 632, and at armature 679 completes a circuit for illuminating the lamp 680 to signal the control operator at the remote operating center. The operator, upon observing the illumination of the lamp 680, answers the call by operating the dial and answer key DAK. Responsive to the operation of key DAK relay 677 is energized by way of springs 665 and said relay at armatures 668 and 671 connects the operator's headset to the left-hand windings of the repeating coil RC4. At armature 669 relay 667 opens the locking circuit of relay 676 whereupon the latter relay deenergizes and opens the circuit extending to the lamp 680, and at armature 670 connects direct ground to the control conductor 600 to cause the energization of relays 501 and 502 in Fig. 6. The circuit for energizing these relays may be traced as follows: from ground through the impulsion springs 661, resting contact of the monitor key MK1, springs 662 and springs 663, normally closed springs controlled by spring 663 of the ringing key RK, through springs 666 of the key DAK, armature 670 and its working contact, through the right-hand windings of the repeating coil RC4, over the single control conductor 600 extending to the local exchange, resting contact of armature 693 and said armature, through the left-hand windings of the repeating coil RC3, conductor 270', conductor 270, through the winding of relays 501 and 504 in series, normally closed springs controlled by armature 588 and through the lower winding of impulsion relay 502 to battery. Relays 502 and 501 only energize over the above-traced circuit. Booster relay 504 is only energized when booster battery is connected to this circuit at the operating center. Relay 502 at armature 518 and its working contact completes a circuit for energizing the slow-to-release relay 505, and the latter relay, upon energizing, at armature 522 connects ground to conductor 267' to maintain relay 631 in operated position. Relay 505 at armature 523 connects ground to conductor 70' to energize slow-to-release relay 506 and the vibrating relay 81 shown in Fig. 1, at armature 521 prepares a point in the circuit for the monitor relay 507, and at armature 524 prepares a point in the impulsion circuit to the local connector. Relay 501 upon energizing at armature 518 opens a point in the circuit extending to the monitor relay 507. Slow-to-release relay 506, upon energizing, at armature 525 prepares a circuit to the release conductor 196 or cut-through conductor 191; at armature 526 disconnects ground from conductor 264' after relay 505 has grounded conductor 267' and at its working contact connects ground to conductor 71' to operate the ringing machine start relay 170 shown in Fig. 2. At armature 527 relay 506 connects ground to conductor 971; and at armature 591 prepares an impulsion circuit to the impulse conductor 972 extending to the divided ringing relay group shown in Fig. 10.

The control operator will now dial the first digit of the called subscriber's number. The calling device CD is therefore operated in accordance with the first digit of the called subscriber's number. As soon as the calling device CD is moved out of its normal position the shunt springs 660 close and connect ground by way of springs 664 through the winding of relay 673 for energizing said relay. At armature 672 relay 673 closes a shunt circuit around the right-hand windings of the repeating coil RC4 to improve the impulsion circuit and at armature 674 disconnects the condenser C' from the impulsion circuit. The relays 501 and 502 therefore follow the impulses, relay 501 operating at this time without effect while at armature 518 impulsion relay 502 completes a circuit for operating the series relay 515 and vertical magnet 111 of the local connector. The circuit may be traced as follows: from armature 518 and its resting contact, armature 524, armature 557, armature 581, through the winding of series relay 515 to battery, through armature 564 and its resting contact, through conductors 190' and 190 to the vertical magnet in the local connector. The operation of the vertical magnet in the local connector raises the switch shaft and wipers opposite the level in which the called line terminates. Series relay 515, upon energizing, at armature 567 completes a circuit for energizing relay 512 by way of armature 565; at armature 569 completes a circuit for energizing relay 514; and at armature 570 closes a shunt around armature 561. Relay 512, upon energizing, at armature 563 closes a short circuit around the change-over relay 513 extending from grounded armature 527 to grounded armature 567. The change-over relay 513 will therefore not energize until the series relay 515 deenergizes after the impulsion period. Relay 514, upon energizing, at armature 568 and its resting contact opens a point in the circuit extending to the test relay 510 and at its working contact prepares a circuit for the busy test relay 511. At armature 595 relay 514 opens a point in the ground-return talking circuit and at armature 596 closes a short circuit around the left-hand winding of the repeating coil RC3 over conductor 900. After the impulsion period relays 502 and 504

581 are maintained energized and therefore relays 515 and 514 deenergize. At armature 567 the de-energization of relay 515 removes the short circuit from around the change-over relay 513 with 5 the result that the change-over relay 513 energizes in series with relay 512 over the following circuit: from grounded armature 527, armature 563 and its working contact, and through the windings of relays 513 and 512 to battery. At 10 armature 564 and its resting contact relay 513 opens the impulsing circuit to the vertical magnet of the local connector and at its working contact prepares a point in the circuit extending to the rotary magnet 110 in the local connector and at armature 565 prepares a circuit for grounding conductor 977. 15

Incidentally, another impulsing circuit is completed by the impulsing relay 502 at armature 517 for operating the counting relays in the divided ringing relay group as follows: each time the impulsing relay 502 deenergizes a circuit may be traced from grounded armature 517, armature 591, to conductor 972. The first impulse extends by way of armature 942 and its resting contact, armature 912 and through the relay 930 to battery. Relay 930, upon energizing, at armature 931 prepares a circuit for energizing relay 940 at the termination of this impulse. Relay 940 will not energize at this time because the same is short circuited as follows: from ground by way of armature 527, conductor 971, armature 931, and from thence over the previously traced circuit to ground at armature 517. At the termination of the first impulse, however, relay 502 is energized and removes ground at armature 517 with the result that relay 940 now energizes in series with relay 930 as follows: from grounded conductor 971, armature 931, through the winding of relay 940, armature 912, and through the winding of relay 930 to battery. The energization of relay 940 at armature 941 prepares a circuit extending to the negative ringing relay 503 over conductor 974 and at armature 942 transfers the impulsing circuit to the second set of counting relays. When the next impulse is received over the impulsing conductor 972 a circuit may be traced from the grounded impulse conductor 972, armature 942 and its working contact, armature 962, armature 913, and through the winding of relay 950 to battery. Relay 950 energizes and at armature 951 prepares a circuit for energizing relay 915 which, however, is short circuited at this time over conductors 971 and 972. At the end of the second impulse ground is removed from conductor 972 with the result that relay 960 energizes in series with relay 950 as follows: from grounded conductor 971, armature 951, winding of relay 950, armature 913 and through the winding of relay 950 to battery. At armature 961 relay 960 prepares a point in the circuit for operating the positive ring relay 509 and at armature 962 opens the impulsing circuit. From the foregoing it will therefore be seen that the first impulse received on the divided ringing relay group selects the negative ring relay 503, that the second impulse selects the positive ring relay 509, and that any other impulses are without effect at this time.

The control operator will now operate the calling device CD in accordance with the second digit 70 of the called subscriber's number. Responsive thereto relays 501 and 502 respond to each impulse in the same manner as previously described. Each time the impulse relay 502 deenergizes a circuit may be traced from grounded armature 75

518 and its resting contact, armature 524, armature 557, armature 561, through the winding of series relay 515 to battery, and from thence by way of armature 564 and its working contact, to conductors 195' and 195 to the rotary magnet 110 in the local connector. By the operation of the rotary magnet 110 the switch shaft and wipers are rotated until the wipers engage the bank contacts of the called line. The energization of relay 515 again operates relay 514 which latter relay 10 at armature 568 opens a point in the circuit to test relay 510 and at its working contact prepares a point in the circuit to the busy relay 511. At armature 567 relay 515 closes a circuit for energizing relay 910 as follows: grounded armature 15 567, armature 565 and its working contact, conductor 977, armature 921, and through the winding of relay 910 to battery. Relay 910, upon energizing, at armatures 912 and 913 opens the circuit of relays 930, 940, 950, and 960 with the result 20 that these latter relays now deenergize. At armature 911 relay 910 prepares a circuit for relay 920 which, however, at this time is short circuited from ground on conductors 971 and 977. After the termination of the impulsing period series 25 relay 515 deenergizes and removes ground from conductor 977 with the result that relay 920 is now energized in series with relay 910 from ground conductor 971. Relay 920, upon energizing, at armature 921 opens a point in its own 30 short circuit and at armatures 922 and 923 prepares a point in the circuit for relays 930 and 950.

Returning now to the common equipment shown in Fig. 6 and at a time when the relay 514 is in energized position after the impulsing period the operation is dependent upon whether the called line is idle or busy. If the called line is idle the busy relay 511 is not energized and when relays 513 and 514 deenergize a circuit is completed for the test relay 510 as follows: from ground by way of armature 527, through the upper winding of relay 510, resting contact of armature 568 and said armature, conductors 189' and 189, to the test wiper 152 of the local connector and thence through the cut-off relay, such as cut-off relay 12, of the called subscriber's line. The cut-off relay 12 of the called subscriber's line and the test relay 510 energize in series, the cut-off relay disconnecting the line relay 11 from the subscriber's line conductor. The energization of test 40 relay 510 at armature 555 and its resting contact opens a point in the release circuit extending over conductor 196' to the local connector and at its working contact prepares a point in the circuit to the cut-through conductor 191' 45 extending to the cut-through relay 105 in the local connector. At armature 557 relay 510 opens a point in the impulsing circuit extending to the local connector and at armature 592 completes a circuit for energizing relay 582 as follows: from grounded armature 527, armature 592, and through the lower winding of relay 582 to battery. Relay 582, upon energizing, at armature 586 completes a temporary circuit through the upper winding of relay 502; at armature 587 completes a circuit for energizing the slow-to-operate relay 581, at armature 590 completes a circuit from grounded armature 527 through the lower winding of relay 582 for maintaining the relay in energized position, and at armature 588 50 substitutes the relay 503 for the lower winding of line relay 502. Relay 503 energizes over the trunk circuit in series with relays 504 and 501 and at armature 519 prepares a circuit for relay 502. After a short interval slow-to-operate re- 55 60 65 70 75

5 lay 582 energizes and closes armature 584 before disconnecting ground from armature 583 and therefore the circuit extending through the lower winding of line relay 502 is completed for maintaining this relay in energized position before the circuit at armature 583 is open through the upper winding of line relay 502.

10 When divided ringing is provided the number of the called subscriber indicates which side of the called line the ringer is connected to and the operator therefore dials either the digit 1 or digit 2 dependent upon whether she wants to ring on the negative side of the line or on the positive side of the line. In case the operator wants to 15 ring on the negative side of the line, the operator will operate the calling device to transmit the digit 1. Responsive to this operation relay 503 deenergizes and in turn deenergizes the line relay 502. The deenergization of relay 502 at armature 517 transmits an impulse over the impulsing conductor 972 for operating relay 930 by way of armature 942 and armature 922 to battery. At armature 931 relay 930 prepares a circuit for 20 energizing relay 940, which, however, is short circuited at this time by way of grounded conductors 971 and 972. At the termination of this impulse when relays 503 and 502 energize ground is removed from the impulse conductor 972 with the result that the short circuit is removed from 25 around relay 940 which thereupon energizes in series with relay 930. At armature 941 relay 940 prepares a point in the circuit for the negative ring relay 508 and at armature 942 transfers the impulsing circuit to relay 950. In case the operator wants to ring on the positive side of the line she will operate the calling device CD in accordance with the digit 2 to transmit two impulses over the impulse conductor 972 whereupon the 30 relays 930 and 940 operate for the first impulse and the second impulse closes a circuit by way of armatures 962 and 923 through the winding of relay 950 to battery. Relay 950 at armature 951 prepares a short circuit for energizing relay 960 which, however, is short circuited at this 35 time by way of grounded conductors 971 and 972. At the termination of the second impulse when relays 503 and 502 reenergize, ground is removed from the impulse conductor 972 with the result that the short circuit is removed from around 40 relay 960 which now energizes in series with relay 950. At armature 961 the relay 960 prepares a circuit for the positive ring relay 509.

45 In order to ring the called subscriber the operator will now operate the ringing key RK in accordance with the code of the called subscriber. Responsive to the operation of the ringing key RK the positive booster battery connection through the lamp L is substituted for the ground connection through the impulse springs 661 at 50 ringing key springs 663. Responsive to the inclusion of this positive booster battery the booster relay 504 for the first time now energizes. Each time the ringing key RK is operated the booster relay 504 energizes and grounds conductor 973, and each time the ringing key RK is restored the resistance R2 is momentarily included in the circuit at a time when the positive booster battery is disconnected to insure the deenergization of booster relay 504. Booster relay 504 is 55 therefore operated and released for each operation and restoration of the key RK to transmit impulses in accordance with the key operations over the conductor 973. These impulses operate either the ringing relay 508 or 509 dependent 60 upon the setting of the divided ringing relay 65

70 group shown in Fig. 10. In case the control operator had dialled the digit 1 after the second digit of the called number then the ground impulses extend by way of conductor 973, armature 961 and its resting contact, armature 941, conductor 974, and through the winding of negative ring relay 508 to battery. In the case where the digit 2 has been dialled after the second digit of the called number then the impulses transmitted over the ringing conductor 973 extend by way 75 of armature 961 and its working contact over conductor 975 to the winding of positive ring relay 509 to battery. The ringing relays 509 or 508 are operated in accordance with the key operations to signal the called subscriber over the negative and positive ring conductors 187' and 187 in the same manner as previously described.

80 Returning now to the point at which the local connector has been rotated into engagement with the called line and at a time when relay 514 is still in the energized position and also at a time when the called line is marked busy. In case the called line is marked busy then the test wiper 152 of the local connector encounters a grounded bank contact with the result that ground is connected to conductor 189' to complete a circuit for energizing the busy relay 511 as follows: from grounded bank contact, wiper 152, armature 129, conductors 189 and 189', armature 568 and its working contact, armature 532, and through the 85 winding of busy relay 511 to battery. At armature 558 busy relay connects the busy tone conductor 233 to the negative talking conductor 185'; at armature 559 connects ground to the positive talking conductor 180' thereby providing a busy tone return path; at armature 560 prepares a point in its own locking circuit; at armature 563 prepares a point in the circuit for energizing relay 582; and at armature 561 opens a point in the 90 impulsing circuit to the local connector. As soon as relay 514 deenergizes after the impulsing period said relay at armature 568 and its resting contact prepares a point in the circuit for the test relay 510 and at the normally closed springs controlled by armature 568 completes the locking circuit for busy relay 511 as follows: from grounded armature 521, armature 560, normally closed springs controlled by armature 568, armature 532 and through the winding of busy relay 511 to battery. At armature 594 relay 514 completes a circuit for energizing relay 582 as follows: grounded armature 521, armatures 594 and 593 and through the lower winding of relay 582 to battery. Relay 582 energizes and accomplishes the same result as previously described. At 95 armature 596 relay 514 removes the short circuit from around the repeating coil RC3 and at armature 595 completes the ground return circuit for enabling talking to take place over the single trunk conductor. The busy tone is now connected to the calling subscriber over the following path: from the busy tone conductor 233, armature 558, to conductors 185' and 185 and thence over the calling subscriber's line back to conductors 186 and 186' to ground at armature 559. 100 Busy tone is also transmitted to the control operator by way of conductor 185', resting contact of armature 529 and said armature, conductors 268' and 268, through the right-hand windings of the repeating coil RC3, to conductors 269' and 269 through armature 531 and its resting contact, to conductor 185', and thence to ground at armature 559. Since the lower left-hand windings of the repeating coil RC3 is connected by way of conductor 270' through armature 595 and the 105

condenser to ground, the busy tone is induced in the left-hand windings of the repeating coil RC3 and from thence over the single conductor 600 through the right-hand windings of the repeating coil RC4 and through the armature 674 and condenser C' to ground. This tone is also induced into the left-hand windings of the repeating coil RC4 and from thence over the heavy talking conductor through armatures 669 and 671 to the operator's headset. When the operator hears the busy tone she will operate her monitor key MK1 to include the resistance R1 in series with the control conductor 600. Responsive to the inclusion of the resistance R1 in the control trunk, the marginal relay 501 is deenergized while the relay 503 is maintained in operated position. Responsive to the deenergization of the marginal relay 501 a circuit is completed by way of armature 518 and its working contact, armature 521, armature 516 and through the winding of monitor relay 507 to battery. Responsive to the operation of the monitor relay 507 the operator may challenge the busy connection if she does not hear any conversation thereon over armatures 523 and 531 in a manner similar to that described for Fig. 4. At armature 532 monitor relay 507 opens the circuit of busy relay 511 with the result that the busy relay now deenergizes. In case the called line is actually in use then the operator will restore the monitor key thereby releasing the monitor relay 507 in response to the energization of relay 501 and will inform the calling subscriber that the called line is busy. It will be noted that due to the deenergization of the busy relay 511 the busy tone was disconnected from both the calling line and the control trunk. In case the control operator hears no response when she challenges the operator will thereupon operate the ringing key RK thereby energizing the booster relay 504 as previously described. Responsive to the energization of booster relay 504 a circuit may now be traced from grounded armature 520, conductor 973, armature 961, and over either conductor 974 or 975 to ringing relays 508 or 509. The operation of either relay 508 or 509 connects ringing current over either of the positive or negative ring conductors 187' or 188' to release the busy local connector in the same manner as previously described. The busy local connection is thereupon released and a circuit may now be traced for energizing the test relay 510 from battery through the cut-off relay of the called line over the connector test wiper 152 and over conductors 189 and 189', armature 568 and its resting contact, through the upper winding of test relay 510 to ground at armature 527. Relay 510 thereupon energizes and performs the same functions as previously described and the operator may now operate her ringing key to ring the called subscriber in the same manner as previously described. The ringing operation from this point on is the same as that just described.

In case the control operator desires to talk with the called subscriber without the calling subscriber hearing, the control operator will operate the monitor key MK1 to operate the monitor relay 507 in the common equipment. When the called subscriber answers the talking circuit between the called subscriber and the control operator is as follows: from the subscriber's called line, wipers 151 and 154 of the local connector, and from thence over the conductors 187, 187', 188, and 188', working contacts of armatures 529 and 531 and said armatures, conductors 268',

268, 269', and 269, through the right-hand winding of the repeating coil RC3. As previously described since the control trunk has a ground return circuit, the voice currents are induced into the left-hand windings of the repeating coil RC3 and thence over the control trunk conductor 600 through the right-hand windings of the repeating coil RC4 and from thence through armature 674, condenser C', to the ground return circuit. These voice currents are likewise induced into the left-hand windings of the repeating coil RC4 and thence through armatures 668 and 671 to the operator's headset. 5

In case the control operator does not wish to wait until the called party answers the monitor key MK1 is therefore not operated and a temporary talking circuit is completed between the calling and called lines as follows: from the called line over the conductors 187, 187', 188, and 188', armatures 533 and 541 and their resting contacts, 20 armatures 552 and 554, over the dotted Y connections, through the resting contacts of armatures 547 and 545 and said armatures, armatures 531 and 529 and their resting contacts, and from thence over the talking conductors 185, 185', 186, 25 and 186' to the calling party. The calling and called parties converse over this talking connection until such time as the operator releases the key DAK, whereupon the relays 501, 503, and later 502 deenergize responsive to the opening of 30 springs 666 to remove ground from the control trunk. At armature 518 the deenergization of relay 502 opens the circuit of slow-to-release relay 505 and the latter relay deenergizes and at armature 523 and its resting contact completes 35 a circuit by way of armature 525 and armature 555 and its working contact over the cut-through conductor 191' for operating the cut-through relay 105 in the local connector. The operation of the cut-through relay 105 in the local connector 40 completes the talking circuit through the repeating coil RC in the local connector in the same manner as previously described. After an interval, slow-to-release relay 506 deenergizes and in turn at armature 527 opens the circuit of relay 45 582, test relay 510, relays 512 and 513, which thereupon deenergize. The deenergization of relay 582 also opens the circuit of relay 581 which likewise deenergizes and the common control equipment in Fig. 6 is now ready for another 50 call. The deenergization of relay 505 opens the locking circuit of relay 631 which likewise deenergizes and the control trunk, the circuits in the distributor, and the common equipment are now 55 ready for another call. Either the calling or called subscriber releases the local connector after conversation in the same manner as previously described.

The common equipment shown in Fig. 6 is also provided with means for rotating the local connector step by step when such local connector is operated to certain levels in which either the trunk lines or toll lines terminate and at each toll or trunk level the normal post springs PS1 or PS2 are operated. Since this circuit is identical with the circuit described for Fig. 4 it is therefore believed unnecessary at this time to explain the circuit operation. 60

In the same manner as previously described the calling subscriber may make his own reverting call or may request the operator to do so for him, so that in the latter case his line may be marked busy to the local connectors having access thereto. In order for the control operator to make a reverting call the operator will dial either 70 75

the digit 1 or the digit 2 to ring on the proper side of the subscriber's line after which she will operate the ringing key in accordance with the code of the called subscriber. The divided ringing relay group shown in Fig. 10 is operated in the same manner as previously described when the operator dials the digit 1 or 2 and when the ringing key is operated in accordance with the code of the called subscriber the booster relay 504 is operated to energize the relay 582 over its upper winding which now locks over its lower winding and performs the same functions as previously described and also operates the proper ringing relay in the same manner as previously described to ring the called subscriber's code. The operation from now on is the same as that previously described and therefore need not be described in detail.

Before describing further detail operations it is believed advisable to describe the talking circuit established between grounded subscriber's lines and metallic lines or vice versa. Assuming now that the magneto telephone shown in the lower circle in Fig. 1 is a grounded subscriber's line, then conductor 22 alone extends to the magneto substation while the conductor 23 does not extend to the substation circuit, it being understood that the substation is grounded in the usual manner as indicated by the dotted connections.

Assuming further that this line is now connected to a called line the talking circuit between the calling and called lines extends as follows: from ground through the substation circuit, conductor 22, wiper 60, conductor 72, armatures 115 and 143, through the right-hand windings of the repeating coil RC, armatures 142, 147, and 119 to conductor 73, wiper 62, to conductor 23 which is grounded. The talking conductor of the metallic called line is connected by way of wipers 151 and 154, armatures 144 and 138, and armature 146 through the left-hand windings of the repeating coil RC2. The bridged listening and talking circuit between a grounded subscriber's line, a metallic subscriber's line, and the control operator before the operator cuts the local connection through is as follows: from ground at the substation, conductor 22, wiper 60, conductor 72, armatures 115, 143, and 127, conductors 185 and 185', armatures 529 and 545, the Y dotted connection, armatures 552 and 538, conductors 187 and 187', armature 128, wiper 151, over the metallic conductors of the called line back to wiper 154, armature 136, conductors 188 and 188', armatures 541 and 554, over the dotted Y connection, armatures 547 and 531, conductors 186' and 186, armatures 137, 147, and 119, conductor 73, wiper 62, to grounded conductor 23. The control operator is connected in bridge of this talking circuit as follows: from armatures 529 and 531 over conductors 268 and 269' to the right-hand windings of the repeating coil RC3; from ground at the remote operating center through the condenser C', armature 674, through the right-hand windings of the repeating coil RC4, trunk conductor 680, armatures 692 and 632, through the left-hand windings of the repeating coil RC3, conductor 270', through armature 595, and over the heavy talking conductor through the condenser to ground return. By means of this bridged listening and talking circuit the calling and called subscribers as well as the control operator may talk to each other. In case the Y dotted connections should be omitted from this circuit then the operator would only be connected to the calling subscriber at this time. In

order to converse with the called subscriber, without the calling subscriber listening in, the control operator will operate her monitor key MK1 to operate the monitor relay 507 and thereby connect her trunk to the called subscriber without being connected to the calling subscriber.

In case it is desired to provide an operator at the local exchange the emergency operating set shown in Fig. 7 is provided. When the transfer key TK is thrown the relay 690 is energized to disconnect the trunk conductor 680 extending to the remote operating center. At armature 691 relay 690 prepares a circuit by means of which the ringing key RK3 may ground conductor 271' to directly operate relay 582 over its upper winding. At armature 692 a circuit is prepared for the call lamp CL and at armature 693 connects the talking circuit to the repeating coil RC5. When a subscriber initiates a call and the finder finds the calling line as previously described relay 207 in the distributor is energized and at armature 232 grounds conductors 263' and 268' for energizing relay 630. At armature 633 relay 630 energizes relay 631, whereupon the energization of relay 631 at armature 637 connects the grounded conductor 263 through the armature 692 to the calling lamp CL and battery. The calling lamp CL is illuminated over the circuit to inform the emergency operator that a call has come in. The emergency operator now operates her dial and answer key DAK1 and at springs 681 and 682 connects up her headset. At springs 684 the following circuit is closed: from ground through the impulse springs 695 of the calling device CD, resistance R5, springs 684, springs of the monitor key MK2, through the right-hand windings of the repeating coil RC5, working contact of armature 693 and said armature, armature 632 and thence over the left-hand windings of the repeating coil RC3 and conductor 270' to relays 501, 504, and 502 in series to battery. The resistance R5 is included in this circuit to prevent the booster relay 504 from energizing. The talking circuit between the calling subscriber is the same as that previously described down to armature 693 and from thence it extends by way of the working contact of armature 693 through the right-hand windings of the repeating coil RC5, shunt springs 694 of the calling device CD and through the condenser C4 to ground. When the emergency operator receives the number of the called subscriber she will operate the calling device in accordance therewith. The shunt springs 694 short circuit the right-hand winding of the repeating coil RC5 by way of resistance R4. The impulsive circuit now extends by way of the grounded impulse springs 695, resistance R5, springs 684, normally closed springs of the monitor key MK2, shunt spring 694 and its working contact, resistance R4, and through the working contact of armature 693 and said armature over the previously traced circuit to the relays in the common operating equipment. The relays in the common operating equipment are operated in the same manner as previously described to extend the connection to the called line. If the emergency operator desires to monitor the connection she will operate the monitor key MK2 to include the resistance R3 in the impulsive circuit and thereby deenergize the marginal relay 501 to cause the relay 507 to energize as previously described. In order to ring the called subscriber the emergency operator will operate the ringing key RK3 after having set the relays in the divided ringing relay group in accordance with the

desired ringing condition and a circuit may now be traced from ground by way of ringing key RK3, armature 691, conductor 271', ringing conductor 973, and thence over armature 961 to either ringing relay 508 or 509 whereupon the called subscriber is rung in the same manner as previously described. After completing the desired connection the emergency operator will release the dial and answer key DAK1 and the local connector is cut through in the same manner as previously described while the distributor and common equipment relays will deenergize and return to normal ready for a new call.

The case will now be considered wherein the 15 ringers are bridged across the subscriber's line, and in this type of system the divided ringing relay group is not needed and the dotted Z wiring is used. When bridged ringing is used only one 20 ringing relay is needed in the common equipment and therefore when the booster relay 504 is operated by the operation of the ringing key 25 said relay at armature 520 completes a circuit by way of the dotted Z wiring to ringing relay 508. The ringing relay 508 therefore is operated in accordance with the ringing code to 30 signal the called subscriber in the same manner as previously described. The dotted Z connection shown directly below relay 512 is provided to enable the ringing relay 508 to operate the reverting relay 106 in the local connector in the same manner as described for Fig. 4.

Toll connections to the local exchange are completed by means of the toll trunk TT shown in Fig. 8 by way of the toll trunk conductors 715 and 716 extending to the toll connector, Fig. 9, 35 located in the local exchange. When the toll operator desires to originate a toll call the toll operator will insert her cord circuit into the jack J at the toll trunk TT thereby disconnecting the drop D and buzzer 104 at jack springs 701 and 40 702. The operator now operates the hold key HK to complete the circuit to the left-hand windings of the repeating coil and to connect ground at spring 107 through the impedance 108 and the normally closed springs controlled by 45 the dial key DK and through the right-hand windings of the repeating coil through the trunk conductors 715 and 716 for energizing relays 807, 808, and 809 in the toll connector. The circuit for energizing line relay 807 extends by way of 50 grounded toll trunk conductor 715, armature 825 and its resting contact, through the upper left-hand winding of the repeating coil in the toll connector, through the upper winding of differential relay 806, and through the winding of line relay 807 to battery. The energizing circuit for relay 808 and marginal relay 809 extends 55 from grounded toll trunk conductors 716, armature 821 and its resting contact, lower left-hand winding of the repeating coil, through the lower winding of the differential relay 806, and through the windings of relays 808 and 809 in series to battery. Differential relay 806 does not energize over this circuit because the two windings are equal and oppose each other. Line relay 60 807, upon energizing, at armature 834 and its working contact completes a circuit for energizing the slow-to-release relay 810. Relay 808, upon energizing, at armature 836 likewise closes a circuit for energizing relay 810, while at armature 835 said relay prepares a point in the circuit for operating relay 802 which, however, is not energized at this time because the marginal relay 809 has also energized and at armature 837 65 has opened the circuit to relay 802. Slow-to-

release relay 810, upon energizing, at armature 839 connects ground by way of busy key 830 to conductor 162 to busy the toll trunk in the banks accessible to the local connectors; at armature 840 connects ground to armature 826, at armature 841 prepares a point in the impulsing circuit; and at armature 842 opens a point in the circuit to the release magnet 817. The toll operator now operates the dial key DK to substitute the ground through the impulse spring 712 of the calling device CD for the ground through the impedance 708 and spring 707. The toll operator now dials the first digit of the called subscriber's number, thereby impulsing the relays 807, 808, and 809. The operations of relays 808 and 809 are without result at this time. Each time line relay 807 deenergizes for each impulse a circuit may be traced from grounded armature 834 and its resting contact, armature 841, off-normal springs 846 and 848, through the winding of vertical series relay 811 and through the winding of vertical magnet 815 to battery. By the operation of the vertical magnet the wipers 862 to 864 of the toll connector are operated step by step opposite the level in which the called line terminates. Relay 811, upon energizing, at armature 844 grounds conductor 162 in order to release any local connector which may have been operated into engagement with this toll trunk and in which such local connector has not been released. The circuit for releasing such local connector extends by way of conductor 163, wiper 153 of the operated local connector, armature 145 on the cut-through relay 105, through the winding of relay 102 to battery. As previously described the operation of relay 102 causes the release of the local connector. At armature 845 and its resting contact relay 811 opens a point in the rotary impulsing circuit and at its working contact opens its original energizing circuit and substitutes a new circuit for itself and vertical magnet 815. In response to the first vertical 40 step of the shaft, off-normal springs 846 and 847 close after which the off-normal springs 45 848 are opened. Since the vertical series relay 811 is a slow-to-release relay, said relay is maintained energized during the vertical impulsing period over the circuit just traced which was substituted by the operation of the off-normal 50 springs. Off-normal springs 838 also close on the first vertical step of the shaft and prepare a point in the circuit to the release magnet 817. A short interval after the transmission of the first series of impulses series relay 811 deenergizes 55 and at armature 845 prepares the impulsing circuit to the rotary magnet 816 and the rotary series relay 813. The operator now dials the second digit of the called number with the result that the line relay 807 now transmits impulses to relay 813 and rotary magnet 816 as follows: from grounded armature 834 and its resting contact, armature 841, off-normal springs 846 and 847, armature 845 and its resting contact, armature 851, armature 860 and from this 60 point through the series relay 813 to battery and through the rotary magnet 816 to battery. By the operation of the rotary magnet 816 the wipers of the toll connector are rotated into engagement with the bank contacts terminating 70 the called subscriber's line. Series relay 813 is slow-to-release and is therefore maintained during the rotary impulsing period and at armature 853 opens a point in the circuit extending to relay 802; at armature 855 closes a shunt 75

around the armature 851 to maintain the rotary impulsing circuit in case the busy relay is energized when test wiper 863 is passing over busy lines; and at armature 854 closes the circuit for 5 the busy relay 812. The operation of the toll connector now depends upon whether the called line is idle or busy.

In case the called line is idle no circuit is completed for the busy relay 812 and when relay 10 813 deenergizes after the rotary impulsing period a circuit may be traced from grounded armature 839, armature 859 and its resting contact, through the upper winding of test relay 814, resting contact of armature 854 and said armature, test wiper 863 in engagement with the test contact terminating the called subscriber's line circuit, conductor 20, and through the winding of the cut-off relay 12 of the called subscriber's line circuit to battery. Cut-off relay 12 and the 15 switching relay 814 energize over the above-traced circuit. Cut-off relay 12 at armature 16 disconnects the line relay 11 from the subscriber's line and at armature 17 connects the grounded conductor 20 over conductor 24 to the finder bank to busy this line to the finders having access thereto and at armature 18 opens a point in the circuit extending to the finder start conductor 30. In the toll connector armature 857 is adjusted to make first and thereupon closes 20 a locking circuit to its lower winding from grounded armature 839. Switching relay 814 after fully operating over its lower winding at armature 858 connects ground to the conductor 20 by way of test wiper 863 to maintain the 25 called line busy to other connectors or finders having access thereto; at armature 859 opens a point in the circuit extending to the busy relay 812; at armature 860 opens a point in the rotary impulsing circuit, and at armatures 856 and 861 30 switches the talking conductors through to talking conductors 19 and 21 of the called subscriber's line.

In case the called line was busy at a time when the wipers were rotated into engagement 45 therewith then a circuit may be traced for energizing the busy relay as follows: from ground connected to the busy test contact of the called line, test wiper 863, armature 854 and its working contact, armature 859 and through the winding of busy relay 812 to battery. Busy relay 812, upon energizing, at armature 849 connects the busy tone conductor 843 to the upper talking conductor, at armature 850 and its working contact prepares a locking circuit for itself; at 50 armature 851 opens a point in the rotary impulsing circuit and at armature 852 connects ground to the lower talking conductor. The busy tone circuit is connected to the right-hand windings of the repeating coil as follows: busy tone conductor 843, armature 849, armature 820 and its resting contact, through the right-hand windings of the repeating coil, resting contact of armature 819 and said armature, to ground at armature 852. A busy tone is induced into the 55 left-hand windings of the repeating coil and is thereby transmitted by way of the resting contacts of armatures 825 and 826 over the toll trunk conductors 715 and 716 to the right-hand windings of the repeating coil in the toll trunk 60 and from thence through the left-hand windings of the repeating coil over the heavy talking conductors through the operator's cord circuit and thence to her headset. When the operator hears the busy tone she will operate her monitor key 65 MK in order to monitor the busy called line to

determine if the called line is actually in use or whether the calling and called subscribers have failed to ring down the connector.

Responsive to the operation of the monitor key MK ground is disconnected from conductor 715 5 with the result that the line relay 807 now de-energizes. Since ground is also disconnected from the upper winding of the differential relay 806, said relay will now energize. Responsive to the deenergization of line relay 807 and the energization of differential relay 806, a circuit may be traced for energizing the switching relay 814 as follows: from ground by way of armature 834 and its resting contact, armature 832 and through the lower winding of switching relay 814 to 10 battery. Relay 814, upon energizing, switches through in the same manner as previously described, and at armature 859 opens the circuit extending to busy relay 812, with the result that the busy relay now deenergizes and removes the 15 busy tone from the trunk line. The operator now listens and if she hears no conversation will challenge to determine if the previously established connection is actually in use. In case the called line is not in use and is only marked 20 busy because the subscribers have failed to ring off on release the operator therefore will receive no response and will operate her ringing key to cause the local connection to be released. Responsive to the operation of the ringing key 25 RK1 ground through the impulse springs is disconnected from the toll trunk conductor 716 with the result that relays 808 and 809 deenergize while the differential relay 806 energizes. A circuit may now be traced from grounded armature 30 836 and its resting contact, armature 831 and through the windings of relays 801 and 805 in multiple to battery. Relay 805, upon energizing, at armature 829 short circuits the alternating current relay 804 while the operation of relay 801 35 connects direct generator by way of the resting contact of armature 822 and said armature, working contact of armature 820 and said armature, armature 856, wiper 862, bank contact 19, through the line wipers and left-hand windings of the 40 repeating coil RC in the local connector, through the alternating current relay 107, and thence back by way of wiper 864, armature 861, armature 819 and its working contact, armature 823 and its resting contact, to generator return. The alternating current relay 107 in the local connector 45 is energized over the above-traced circuit and closes a circuit for energizing relay 102 whereupon the local connector is released in the same manner as previously described. Thus ringing current is induced back through the condensers normally shunted by armatures 820 and 819 through the right-hand windings of the repeating coil in the toll connector and from thence through the left-hand windings of the repeating coil over 50 the toll trunk to the toll operator. After having released the local connector or after connection with an idle line the operator will operate either ringing key dependent on whether the ringer of the called subscriber is connected to the negative line conductor of the positive line conductor to ground. In case the ringer of the called subscriber is connected to the negative side of the line and ground the operator will operate the ringing key RK1 in accordance with the code 55 of the called subscriber. Relays 806, 807, and 801 are operated in accordance with the operation of the ringing key RK1 and relay 801 connects direct generator by way of wiper 862 over 60 the negative talking conductor on the called line 65 70 75

and from thence through the subscriber's ringer to ground. In case the ringer of the called subscriber is connected to the positive side of the line and ground then the operator will operate 5 the ringing key RK2 whereupon the resistance 150 is included in the circuit extending over the toll trunk conductor 716 whereupon the marginal relay 809 deenergizes and at armature 837 completes a circuit for energizing the reverse ringing 10 relay 802 as follows: from ground by way of armature 838, armature 837, armature 835, and through the winding of relay 802 to battery. Relay 802, upon energizing, at armature 824 closes a circuit for energizing relay 801 and at armatures 15 822 and 823 reverses the generator connection so that direct generator is connected to the positive talking conductor of the called subscriber's line as follows: from direct generator by way of the working contact of armature 823 and said 20 armature, working contact of armature 819 and said armature, armature 831, wiper 864 and thence over the positive talking conductor of the called subscriber's line through the substation ringer to ground. Since the relays 802 and 801 25 are operated in accordance with the operations of the key RK2, the subscriber's ringer is operated to ring his code. After the operation of the ringing key the relay 806 again deenergizes while relay 809 again energizes. The operator can 30 now restore her dial key DK and ground through the impedance 708 and springs 707 will be substituted for the ground through the impedance springs 712. When the called subscriber answers the connection is completed by the toll operator 35 in the usual manner.

The toll connector is provided with a busy key 830 by means of which this particular toll trunk is made busy in the banks of the local connector by connecting ground to conductor 162. In a 40 similar manner the local finder connector links are made busy by the busy key therein which key at springs 124 connects ground to the guard conductor 65 to render such finder connector link busy.

45 After the termination of conversation the called subscriber will operate his hand generator thereby transmitting ringing current over the heavy talking conductor and through the windings of the repeating coil in the toll connector and the alternating current relay 804 to cause the energization of the latter relay. At armature 823 relay 804 closes a circuit for energizing relay 803 which at 50 armatures 825 and 827 and their working contacts connect direct generator across the toll trunk conductors 715 and 716 through the right-hand windings of the repeating coil in the toll trunk from where it is induced into the left-hand winding of the repeating coil and over the heavy talking conductor and through the supervisory equipment in the operator's cord circuit to signal the operator thereof of the termination of the conversation. The toll operator will thereupon remove her cord circuit from the jack J and restore the hold key HK thereupon disconnecting ground 55 at springs 707 from the conductors 715 and 716 with the result that relays 807, 808, and 809 de-energize. Responsive to the deenergization of relays 807 and 809 slow-to-release relay 810 de-energizes after an interval and at armature 843 completes a circuit through the off-normal springs 838 for energizing the release magnet 817. At armature 839 ground is disconnected from conductor 162 to again mark the toll trunk idle and to open the locking circuit of switching relay 814 60 which thereupon deenergizes. Responsive to the 75

operation of the release magnet 817 the wipers and switch shaft are restored to their normal position where the off-normal springs are operated to the position shown in the drawings at which time the off-normal springs 838 open the circuit to the release magnet 817. The toll trunk and connector are now therefore returned to their normal positions and may be used in other connections. In a manner similar to that just described the toll operator may remove the cord circuit from the jack J and release the hold key HK to cause the deenergization of the toll connector without waiting for the called subscriber to indicate the termination of conversation.

Having described the invention what is considered to be new and is desired to have protected by Letters Patent will be set forth in the following claims.

What is claimed is:

1. In a telephone system wherein an operator 20 remote from a local exchange controls automatic switches in the local exchange over a common control trunk to complete direct connections between local subscribers' lines, splitting means common to all said switches in the local exchange, 25 and operator controlled means for controlling said common splitting means by way of said control trunk to enable the operator to talk to either the local calling or the local called subscriber to the exclusion of the other subscriber.

2. In a telephone system wherein an operator 30 at a main exchange remote from a local exchange controls automatic switches in the local exchange over a common control trunk to complete direct connections between local subscribers' 35 lines, means in the local exchange for temporarily completing a talking circuit including a portion of said control trunk connected in series between the local calling and called subscribers' lines with the control trunk conductors bridged 40 across such portion.

3. In a telephone system wherein an operator 45 remote from a local exchange controls automatic switches in the local exchange over a common control trunk to complete direct connections between local subscribers' lines, means in the local exchange for temporarily completing a talking circuit including a portion of the control trunk connected in series between the local calling and called subscribers' lines with the control trunk conductors bridged across such portion, and operator controlled means for completing a direct talking circuit between the local subscribers' lines excluding the said portion of said control trunk.

4. In a telephone system wherein an operator 55 remote from a local exchange controls automatic switches in the local exchange over a common control trunk to complete direct connections between local subscribers' lines, means in the local exchange for temporarily completing a talking circuit including a portion of the control trunk connected in series between the local calling and called subscribers' lines with the control trunk conductors bridge across such portion, and operator controlled means in the local exchange for 60 completing a talking circuit between the called subscriber's line and the control trunk excluding the calling subscribers' line.

5. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for auto- 75

- 5 matically signalling the remote operator over said control trunk, means controlled by the operator for operating one of said switches into connection with the called line, means for transmitting a busy tone to the calling subscriber and the operator in case the called line is busy, and means for enabling the operator to listen in on the busy connection by way of said operated switch.
- 10 6. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over the control trunk, means controlled by the operator for operating one of said switches into connection with the called line, means for transmitting a busy tone to the calling subscriber and the operator in case the called line is busy, means for enabling the operator to listen in on the busy connection by way of said operated switch, and means for preventing the calling subscriber hearing the conversation when the operator enters the busy connection.
- 15 7. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk, means controlled by the operator for operating one of said switches into connection with the called line, means for transmitting a busy tone to the calling subscriber and the operator in case the called line is busy, means for enabling the operator to listen in on the busy connection by way of said operated switch, means for preventing the calling subscriber hearing the conversation when the operator enters the busy connection, and means for removing the busy tone when the operator enters a busy connection.
- 20 8. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk, means controlled by the operator for operating one of said switches into connection with the called line, means for transmitting a busy tone to the calling subscriber and the operator in case the called line is busy, means for enabling the operator to listen in on the busy connection by way of said operated switch, and means for enabling the operator to release the busy connection by way of said operated switch.
- 25 9. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk, means controlled by the operator for operating one of said switches into connection with the called line, means for transmitting a busy tone to the calling subscriber and the operator in case the called line is busy, and means for enabling the operator to listen in on the busy connection by way of said operated switch.
- 30 10. In a telephone system wherein an operator remote from a local exchange controls automatic switches in the local exchange over a common control trunk to complete direct connections between local subscribers' lines, means responsive to a local subscriber calling for automatically signalling the remote operator over the control trunk in case the control trunk is idle and for storing such call in case the control trunk is busy, and means in the local exchange for transmitting a waiting tone over the control trunk to the remote operator in case any calls are stored while the control trunk is in use in completing a preceding call.
- 35 11. In a telephone system wherein an operator remote from a local exchange controls automatic switches in the local exchange over a common control trunk to complete direct connections between local subscribers' lines, and means in the local exchange for transmitting a waiting tone over the control trunk to the operator responsive to a second calling subscriber initiating a call before the operator has completed the connection desired by a preceding calling subscriber.
- 40 12. In a telephone system wherein an operator remote from a local exchange controls automatic switches in the local exchange over a common control trunk to complete direct connections between local subscribers' lines, means responsive to a local subscriber calling for signalling the remote operator over the control trunk, and ringing means at the local exchange controlled over said control trunk by the operator for transmitting ringing current back over the calling subscriber's line to ring the called subscriber without directly operating any automatic switch in case the called subscriber's substation is on the same line as the calling substation.
- 45 13. In a telephone system, a local exchange comprising a plurality of automatic switches and a common control apparatus for controlling the automatic switches therein, a control trunk extending from the said common apparatus to an operator's position in a remote operating center, means at the operator's position for controlling said apparatus over said control trunk to operate said switches to complete connections between local subscribers' lines, and means at the local exchange controlled by the remote operator over said control trunk for selectively connecting ringing current to either line conductor of a called subscriber's line.
- 50 14. In a telephone system, a local exchange, a remote operating center, a control conductor extending from said local exchange to said remote operating center, automatic switches at said local exchange controlled over said control trunk by an operator at the operating center to complete connections between local subscribers' lines, and means at the local exchange controlled over said control trunk by the remote operator for selectively connecting ringing current to either line conductor of a called subscriber's line.
- 55 15. In a telephone system, a local exchange comprising two similar units of exchange equip-

- ment, each unit including a plurality of automatic switches, a common control apparatus individual to each unit for controlling the automatic switches therein, switching means in said local exchange having access to each common control apparatus in each unit, a single control trunk extending from an operator's position at a remote operating center and terminating in said switching means at said local exchange, said switching means automatically operated in response to a call for switching the control trunk to the common control apparatus of the unit in which the calling line is located, and means for operating the connected common control apparatus over said control trunk to operate the automatic switches in the connected unit to complete a connection.
16. In a telephone system wherein an operator remote from a local exchange controls automatic switches in the local exchange over a common control trunk to complete direct connections between local subscribers' lines in response to any local subscriber initiating a call, local paystation subscribers' lines also terminating in the local exchange, paystation tone generating means in the local exchange, means responsive to a paystation line initiating a call for connecting said tone generating means to the paystation line, means responsive to the control operator answering the initiation of the paystation call for operating said tone generating means to transmit a paystation tone over the connection to the paystation line and over the control trunk to the operator, and a timing means operated a predetermined time after the operator answers for disconnecting the paystation tone from said paystation line.
17. In a telephone system wherein an operator remote from a local exchange controls automatic switches in the local exchange over a common control trunk to complete direct connections between local subscribers' lines in response to any local subscriber initiating a call, means in the local exchange controlled by the remote operator over the control trunk for simulating the initiation of a call from the local exchange, and means operative responsive thereto for enabling the control operator to control the operation of one of said automatic switches to complete a connection to a desired local subscriber's line.
18. In a telephone system, a local exchange, local subscribers' lines terminating in said exchange, a plurality of finder-connector links for completing connections between said lines, a control trunk common to said links extending from said local exchange to an operator's position in a remote operating center, means responsive to a local subscriber calling for operating a finder of an idle finder-connector link to find the calling line, for signalling the operator over said control trunk, and for connecting the calling line to said control trunk, means responsive to the remote operator answering and dialling the number of the called line for operating the associated connector switch of said link to extend a connection to the called line, means controlled by the operator over said control trunk for ringing the called subscriber, a talking circuit including a portion of said control trunk connected in series between the finder and connector of the link for connecting the calling and called subscribers and the operator, operator controlled means for disconnecting said control trunk from said finder-connector link, means operated responsive to said disconnecting means for excluding said portion of the control trunk from said talking circuit to complete a direct talking circuit between said lines including only the finder and connector of said link, and means responsive to said finder finding the calling line for preselecting an idle one of said finder-connector links.
19. In a telephone system wherein an operator remote from a local exchange controls automatic step-by-step switches in the local exchange over a common control trunk to complete direct connections excluding the control trunk between local calling subscribers' lines and a group of trunk lines, means in the local exchange common to said switches and controlled by the operator over the common control trunk for operating said switches into connection with the first trunk line in the group, and means operated responsive thereto for enabling the operator to operate said switches one step at a time in case the engaged trunk line is busy until an idle trunk line in the group is found.
20. In a telephone system, a calling line, finder switches having access to said line, a pair of relays, means responsive to a call on said line for operating an idle one of said finders to find the calling line and for operating the first of said relays, means controlled by said first relay for operating said second relay, and means controlled by said second relay for interrupting the circuit of the first relay whereby said relays alternately interrupt each other to transmit a tick tone to the calling line until the finder finds the calling line.
21. In a telephone system, a local exchange, subscriber party lines in the local exchange, a distant main exchange, an operator's position at the main exchange, a control trunk connecting the operator's position to the local exchange, automatic switches in the local exchange having access to said lines, a first ringing means in said local exchange for connecting ringing current to the negative line conductor of a called line through said switches, a second ringing means in said local exchange for connecting ringing current to the positive line conductor of a called line through said switches, means in the local exchange operated in response to impulses transmitted over the control trunk from the operator's position for operating one of said switches to connect with a called one of said party lines and for selecting a particular one of said ringing means in accordance with the impulses transmitted, a ringing key at the operator's position, and means at the local exchange operated over said control trunk in response to the operations of said key for operating the selected ringing means to connect ringing current to corresponding line conductor of the called line to code ring a desired subscriber on said line in accordance with the actuations of said key.
22. In a telephone system, subscriber party lines, automatic switches having access to said lines, a first ringing means for connecting ringing current to the negative line conductor of a called line through said switches, a second ringing means for connecting ringing current to the positive line conductor of a called line through said switches, means operated in response to received impulses for operating one of said switches to connect with a called one of said party lines and for selecting a particular one of said ringing means in accordance with the impulses received, a ringing key, and means operated in response to operations of said key for operating the selected ringing means to connect ringing

current to the corresponding line conductor of said called line to code ring a desired subscriber on said line in accordance with the actuations of said key and the operated ringing means.

5 23. In a telephone system, a called party line having two line conductors, two groups of subscribers' substations connected to said line, the first group having their ringers connected to one line conductor of said line and ground, the second 10 group having their ringers connected to the other line conductor of said line and ground, a first ringing means for connecting ringing current to said one line conductor of said called line to operate the ringers of the first group, a second 15 ringing means for connecting ringing current to said other line conductor of the called line to operate the ringers of the second group, means operated in response to received impulses for selecting a particular one of said ringing means in 20 accordance with the impulses received, a ringing key, and means operated in response to operations of said key for operating the selected ringing means to connect ringing current to the corresponding line conductor of the called line to code ring a subscriber in either group in accordance with the actuations of said key and the operated ringing means.

24. In a telephone system, a local exchange, subscriber party lines in the local exchange, a 30 distant main exchange, an operator's position at the main exchange, a control trunk connecting the operator's position to the local exchanges, automatic switches in the local exchange having access to said lines, a first ringing means in said 35 local exchange for connecting ringing current to the negative line conductor of a called line through said switches, a second ringing means in said local exchange for connecting ringing current to the positive line conductor of a called line through said switches, means in the local 40 exchange operated in response to impulses transmitted over said control trunk from said operator's position for operating one of said switches to connect with a called one of said party lines, a first ringing key and a second ringing key at the operator's position, means at the local exchange operated 45 over said control trunk in response to operations of said first key for operating said first ringing means to connect ringing current to the negative line conductor of said called line to code ring a desired subscriber on said line in accordance with the actuations of said first key, and means at the local exchange operated 50 over said control trunk in response to operations of said second ringing key for operating said second ringing means to connect ringing current to the positive line conductor of the called line

to code ring a desired subscriber on said line in accordance with the actuations of the second key.

25. In a telephone system, a called party line having two line conductors, two groups of subscribers' substations connected to said line, the first group having their ringers connected to one line conductor and ground, the second group having their ringers connected to the other line conductor and ground, means responsive to received impulses for selecting and connecting with said 10 called line, a first ringing key, a second ringing key, means controlled by the operations of said first ringing key for connecting ringing current to said one line conductor to operate the substation ringers in the first group to code ring a desired 15 subscriber therein, and means controlled by the operations of the second ringing key for connecting ringing current to said other line conductor to operate the substation ringers in the second group to code ring a desired subscriber therein. 20

26. In a telephone system, a local exchange, local party lines terminating in the local exchange, automatic switches having access to said lines, a control trunk comprising only a single control conductor and a ground return circuit 25 extending from said local exchange to an operator's position in a remote operating center, means at the local exchange for connecting said control trunk to one of said switches in response to the initiation of a call on one of said party 30 lines, means at the remote operating center operated over said single control conductor for signaling the operator thereat in response to the connection of said control trunk to said switch, means at the local exchange operated over said 35 single control conductor for operating said switch to connect with a called party line in response to line selecting impulses transmitted from the operator's position, a ringing key at the operator's position, means at the local exchange operated over said 40 single control conductor for selectively connecting ringing current to either line conductor of said called party line to selectively code ring a subscriber thereon in response to ringing selecting impulses transmitted from said operator's position and actuations of said ringing key in accordance with the code of the desired subscriber, a monitor key at the operator's position, means at said local exchange operated over said 45 single control conductor for monitoring the connection between the calling and called lines over said control trunk in response to the operation of said monitor key, and means at the local exchange operated over said single control conductor for disconnecting said control trunk from 50 said switch. 55

EDWARD S. PETERSON.
